UNITED STATES PATENT OFFICE.

CHARLES M. MANLY, OF NEW YORK, N. Y.

VARIABLE-SPEED-TRANSMITTING MECHANISM.

1,317,719.

Specification of Letters Patent.

Patented Oct. 7, 1919.

Application filed October 31, 1907. Serial No. 399,969.

To all whom it may concern:

Be it known that I, CHARLES M. MANLY, a citizen of the United States, residing in the city of New York, county and State of New York, have invented certain new and useful Improvements in Variable-Speed-Transmitting Mechanism, of which the following is a specification.

My present invention is an improvement 10 in variable speed transmitting mechanisms of the class shown and described in my Letters Patent No. 710,485, dated October 7, 1902, and No. 801,097, dated October 3, 1905, in which a pumping device and a motor operated by fluid delivered from the pump, are interposed between a prime mover and a driven device, whereby the driven device may be caused to operate at any and all speeds in both directions with a torque inversely proportional to its speed, without requiring changes either in the speed, direction of rotation, or power of the prime mover.

One object of my invention is to provide 25 improved, simple and effective means in such mechanisms for varying at will the velocity ratio of the driven device to the prime mover; a further object is to provide means whereby, when the pump and 30 motor shafts are revolving in the same direction at substantially the same speed, the said shafts will be automatically locked together and when they cease to revolve at equal speeds will be automatically unlocked.

With these and other objects in view, my invention consists of an improved speed transmitting mechanism embodying a pump driven from any external source of power, a motor connected to the pump by a fluid 40 and adapted to be connected to a driven device and means for adjusting the relative capacities of the pump and the motor, as hereinafter more particularly pointed out in the claims; and it further consists in 45 means for locking together the pump and the motor when they are revolving at the same speed in the same direction, and finally, in the novel construction and details herein- 50 after described, with reference to the accompanying drawings and more particularly pointed out in the claims.

In the drawings, illustrating a preferred form in which my invention may be carried out:

55 Figure 1 is a partial longitudinal sectional view through the pump;

Fig. 2 is a longitudinal sectional view through the motor;

Fig. 3 is a transverse sectional view on the line 3—3, Fig. 1, looking in the direction 60 of the arrows;

Fig. 4 is a partial transverse sectional view on the line 4—4, Fig. 1, looking in the direction of the arrows;

Fig. 5 is a partial transverse sectional 65 view on the broken line 5—5, Fig. 1, looking in the direction of the arrows;

Fig. 6 is a side elevation of the main valve of the pump hereinafter referred to;

Fig. 7 is an enlarged sectional view on 70 the line 7—7, Fig. 1, looking in the direction of the arrows;

Figs. 8, 9 and 10 illustrate on a smaller scale the parts of Fig. 7 in different relative positions as hereinafter more fully described;

Fig. 11 is a transverse sectional view on the line 11—11, Fig. 1, looking in the direction of the arrows;

Fig. 12 is a partial sectional view on the 80 line 12—12, Fig. 11;

Fig. 13 is a side elevation of Fig. 12 looking in the direction of the arrow 13;

Figs. 14, 15, 16 and 17 are detail views 85 of Fig. 12, hereinafter more particularly referred to;

Fig. 18, Sheet 3, is a central longitudinal sectional view on a larger scale of part of the left hand end of Fig. 1;

Fig. 19, Sheet 3, is a transverse sectional 90 view on the line 19, Fig. 18, looking in the direction of the arrow;

Fig. 20 is a sectional view on a larger scale of certain control valves shown in 95 elevation in Fig. 1;

Fig. 21 is a sectional plan view on the line 21—21, Fig. 20, looking in the direction of the arrows;

Fig. 22 is a sectional elevation on the line 22—22, Fig. 21;

Fig. 23 is a partial transverse sectional 100 view on the line 23—23, Fig. 1;

Fig. 24 is a side elevation of Fig. 23; and

Figs. 25 and 26, Sheet 3, and Fig. 27, Sheet 4, are detail views hereinafter referred to;

Fig. 28 is an enlarged detail view, similar to Fig. 16; and

Fig. 29 is an enlarged detail view of certain parts shown in Fig. 1.

Referring now to the drawings, in which the same reference characters relate to the

same or corresponding parts in all the views, the numeral 30 indicates the main pump casting comprising three radial cylinders, 31, 32, and 33, arranged equidistantly around the central crank chamber 34, the said cylinders being provided with ports 35, 36 and 37, respectively, connecting them to the central crank chamber 34, see Figs. 1, 3 and 5. Journaled in bearings 38 and 39 is a crank shaft 40 embodying a crank pin 41 provided with a bushing 42, on the exterior of which is mounted a bushing 43, for convenience designated the "eccentric bush," the bore of which has an eccentricity, in respect to the outer circumference of the bush, equal to the eccentricity of the crank pin 41 with respect to the crank shaft 40. Rotatably mounted on the eccentric bush 43 are pitman rods 44, 45 and 46 connected by the pins 47, 48 and 49, respectively, to pistons 50, 51 and 52 slidably mounted in pump cylinders 31, 32 and 33, respectively. When the eccentric bush 43 is maintained in such a position on the crank pin 41 that its outer circumference is eccentric to the crank shaft 40, rotation of said crank shaft 40 causes the pistons 50, 51 and 52 to reciprocate in their respective cylinders 31, 32 and 33, the pitman rods 44, 45 and 46 being confined in their bearings on the eccentric bush 43 by annular rings 53 and 54, the former of which is integral with the left hand end of the eccentric bush 43, while the latter is connected to the right hand end of the said eccentric bush 43 by means of a pin 55 seated in a hole in said bush 43 and engaging a recess in said ring 54, as shown in Fig. 1. When the pistons 50, 51 and 52 are thus reciprocated they draw in fluid on their inner strokes and force it out on their outer strokes through their respective ports 35, 36 and 37, the ingress and egress of such fluid being controlled by a main rotary valve 56 mounted in the bore of the crank chamber 34. This valve 56 is provided with two ports 57 and 58. With the ports in the relative positions shown in the drawings and assuming the crank shaft 40 to revolve in a clockwise direction as viewed from the left hand end of Fig. 1, the inlet port is 57 and the outlet port is 58, the inlet port 57 being at all times during the rotation of the valve connected, through the channel 59 formed in the interior of the valve, with the inlet pipe 60, while the said outlet port 58 is similarly connected at all times through its channel 61 with the outlet pipe 62, the valve 56 being maintained in its proper position, with respect to the crank pin 41, for the proper ingress and egress of fluid by suitable connections, hereinafter described, between the eccentric bush and the said valve 56. The inlet and outlet ports 57 and 58, respectively, of the main valve 56 are diametrically opposite (Fig. 5), being separated by a central web 350 which at diametrically

opposite points broadens out into two bridges 351 and 352, respectively, each of which is of a circumferential width equal to the circumferential width of the ports 35, 36 and 37 leading from their respective cylinders. In Figs. 1 and 5, the main valve 56 is shown in such a position that the said bridge 351 just completely closes the port 35 leading from the cylinder 31, the port 36 leading from the cylinder 32 being connected to the outlet port 58 while the port 37 leading from the cylinder 33 is connected to the inlet port 57, the lower bridge 352 of the valve, being midway between the cylinder ports 36 and 37, and since the piston 50 is at the upper end of its stroke where there is momentarily neither ingress nor egress of fluid, its port 35 is properly disconnected from both ports of the valve. When the crank shaft 40 is rotated as above, the port 57 being the inlet port and the port 58 the outlet port, it is evident that immediately that the valve is displaced from the position there shown, the port 35 becomes connected to the inlet port 57 of the valve whereby fluid is free to pass from the inlet pipe 60 through the channel 59 into the port 35 until the piston 50 reaches the lower end of its stroke, and since such motion of the piston occupies one-half revolution of the crank shaft it is readily seen that, if the valve has been rotated simultaneously through 180 degrees, the port 35 at this moment will be cut off from communication with the inlet port 57 and be prevented from communicating with the outlet port 58 from the fact that the said port 35 is just covered by the bridge 352 of the valve. Similarly during the outward stroke of the piston 50 the port 58 of the valve will be maintained in communication with the port 35, until the moment the piston reaches the outer end of its stroke when the valve reaches the position shown in the drawings where the port 35 is again cut off by the bridge 351. In a corresponding manner the ports 36 and 37 are maintained in communication with the inlet port 57 of the valve during the inward strokes of their respective pistons 51 and 52, and with the outlet port 58 during the outward strokes, one valve thereby serving to control the fluid passing in and out of all the cylinders. The inlet channel 59 is always in communication with the inlet pipe 60 and the outlet channel 61 is always in communication with the outlet pipe 62, and so far as fluid pressure in these two channels is concerned the valve as described is balanced. In order to balance the valve with respect to its ports 57 and 58 so that the pressure of the fluid will in no way tend to cause the valve to be forced to one side or the other, I provide the balance grooves 63, 64, 65 and 66 formed in the outer periphery of the valve, the two balance ports 63 and

64 being each equal in width to one-half the width of the port 58 and of a circumferential length equal to the circumferential length of the port 58 and symmetrically arranged with reference to a center line passing through the port 58, the two balance ports 65 and 66 being similarly arranged on the opposite side of the valve and similarly proportioned with respect to the port 57. The balance ports 63 and 64 are connected to the port 58 by suitable holes 67 and 68, and the two balance ports 65 and 66 are connected to the port 57 by the holes 69 and 70, drilled through the body of the web 350 in such a way as to prevent improper communication between them. Formed in the inner wall of the crank chamber 34 are subsidiary balance ports 71, 72, 74 and 76 and the two ports not shown but similar to and in the same plane as port 71 and arranged in the same manner as ports 72, 74 and 76, diametrically opposite the respective cylinder ports 35, 36 and 37, each of which subsidiary balance ports is one-half the width of a cylinder port 35, 36 or 37, and has a circumferential length equal to that of such cylinder port, the subsidiary balance ports 72, 74 and 76 being in line with the balance ports 64 and 66 and the subsidiary balance ports 71 and the two ports not shown but corresponding to ports 74 and 76, in line with the balance ports 63 and 65 of the main valve 56. Supposing pressure to exist in the pressure or outlet port 58 of the valve, which implies in turn that there is pressure in the cylinder port 36, the valve would be subjected to a side pressure tending to displace it to the left in Fig. 5, the extent of the side pressure tending to thus displace it being determined by the width of the port 58 and the circumferential distance from the corner of the upper bridge 351 to the lower corner of the port 36, which in this case would be 120 degrees. Since, however, the balance ports 63 and 64 are connected to the port 58 they are also under the same pressure as the port 58 and since they circumferentially overlap the subsidiary balance port 74 and its companion port, not shown, to the same extent that the port 58 overlaps the port 36, the valve 56 is thereby subjected to a pressure tending to displace it toward the right equal to that tending to displace it toward the left and it is, therefore, in balance. Similarly for other positions of the valve 56 the balance ports of the valve co-acting with the subsidiary balance ports cause the valve to be always balanced, for when the port 58 is in communication with both the cylinder port 36 and the cylinder port 37 the balance ports 63 and 64 are in an exactly corresponding position with reference to the subsidiary balance ports 74, 76 and the two corresponding ports, not shown, respectively.

65 In order to maintain the main valve 56 of the pump in its proper angular position with reference to the real crank both during rotation and adjustment of the length of stroke of the said crank, the said valve 56 is not driven directly by the crank shaft 40 70 on which it is mounted, but is driven through a connection with the eccentric bush 43 in a manner which I will now describe. Integral with the annular ring 54, see Fig. 1, is an eccentric 320, the center of 75 which is coincident with the center of the exterior circumference of the eccentric bush 43. To the right of this eccentric 320 and integral with it is a second eccentric 321, the center of which, where the parts are in 80 the positions shown, is coincident with the center of the crank shaft 40; the annular ring 54 is counter-bored at its right end to bear on the crank arm 322, the circumference of which is concentric with the crank pin 41, the said crank arm merely acting as an additional support for preventing displacement of the annular ring 54. Mounted on the eccentric 320, and more clearly seen in the enlarged view Fig. 7, is a shoe 323, and mounted on the eccentric 321 is a similar shoe 324. To the right of these eccentrics in Fig. 1 is a circular plate 325, terminating in a tubular sleeve 326 in which is a bushing 327 in which the crank shaft 40 is journaled. 95 The end of the sleeve 326 is rigidly fastened to the main valve 56 so that the said valve always moves with the said sleeve. In the left face of the circular plate 325 is a vertical slot 328 made equal in width to the 100 width of the shoe 323 surrounding the eccentric 320 and in depth equal to the thickness of the said shoe. Formed in the same plate 325 and perpendicular to the said slot 328, but in a different plane, is a slot 329 105 made equal in width to the shoe 324 mounted on the eccentric 321, the said shoes 323 and 324 being slidably mounted in said slots 328 and 329. If the crank shaft 40 for the moment be considered stationary and the eccentric bush be adjusted in a clockwise direction, as viewed from the left hand end of Fig. 1, the eccentric 320 will cause the shoe 323 to press against the sides of the slot 328 in the plate 325, and thereby turn the said 110 plate in the same direction. The said plate, however, will not turn as rapidly as the said eccentric bush, its speed of adjustment being only one-half that of the said bush. In Fig. 8, drawn to the same scale as Fig. 1, I have shown the eccentric 320 (which is concentric with the exterior circumference of the eccentric bush 43 and turns at the same rate that it does) as adjusted through 90° in a clockwise direction from the position shown in Fig. 7, and it will be seen that the slot 328 which was vertical has not rotated through 90° but through only 45°. In Fig. 9 the eccentric 320 has been rotated through 180° from its position in Fig. 7 and 115 120 125 130

the slot 328 in the plate 325 has rotated through only 90° . Similarly, in Fig. 10, while the eccentric 320 has been rotated through 240° the plate 325 has been rotated 5 through only 120° , and since the valve is rigidly connected to the said plate 325 by means of the sleeve 326, the said valve has only been rotated one-half as fast as the eccentric 320, and consequently only one-half 10 as fast as the eccentric bush 43. The object of the second eccentric 321 is apparent in Fig. 9, where the eccentric 320 having arrived at the position where it is concentric with the plate 325 is not in an advantageous 15 position for causing further movement of the plate 325, but the eccentric 321, which in Figs. 1 and 7 was concentric with the crank shaft 40 and with the circular plate 325, has now reached its position of maximum 20 eccentricity with reference to the said shaft 40, and, therefore, it is in its most advantageous position for causing its shoe 324 to turn the plate 325. It is apparent that as either eccentric moves from its position 25 of greatest advantage for turning the plate 325 the other one moves toward its most advantageous position and at no time is there any difficulty in the combination of the two eccentrics causing the plate 325 to be adjusted at its proper speed of one-half 30 the rate of adjustment of the eccentric bush.

Referring again to Fig. 7 *a* is the main center of the pump and of the crank shaft 40, *b* is the center of the crank pin 41 and of the eccentric bore in the bush 43, *c* is the center of the exterior circumference of the eccentric bush 43 and of the eccentric 320, *d* is the center of the exterior circumference of the eccentric 321, and the real throw 40 of the crank, so far as the reciprocation of the pistons in the cylinders is concerned, is the distance from *a* to *c*. In the preceding description I have stated that the main valve 56 is maintained in its proper 45 angular position with reference to the "real" crank of the pump, and I have also shown how the said valve 56 is adjusted at only one-half the angular rate that the eccentric bush 43 is adjusted. Since, however, the 50 valve 56 must act to connect the pump cylinders to the proper side of the fluid connection at the same point in the cycle, no matter what the length of stroke of the crank, the said valve 56 must always be maintained 55 in its same angular position with reference to the real crank. Referring now to Figs. 8, 9 and 10, it will be seen that in the adjustment of the eccentric bush 43 the real crank and the valve do move together, for the real 60 crank being the distance from *a* to *c* and its direction in line from *a* to *c*, this line *a* to *c* is always maintained parallel to the sides of the slot 328 in the plate 325. It should be noted, however, that in Fig. 9, 65 owing to the rotation of the eccentric 320

through 180° , the center *c* has been brought to coincide with the center *a*, and therefore there is no real crank, the eccentric 320, and, therefore, the outer circumference of the eccentric bush being now concentric with the 70 center of the crank shaft 40. In this position there is consequently no reciprocation of the pistons in the pump cylinders.

Further rotation of the eccentric 320 immediately causes the center *c* to pass from 75 its position of coincidence with the center *a* and, as a result, the eccentric 320 and consequently the outer circumference of the eccentric bush is no longer concentric with the crank shaft 40 and consequently the real 80 crank again has stroke and the pistons are, therefore, caused to reciprocate by the rotation of the shaft 40. Fig. 10 shows one such position where the center *c* has passed through the position where it is coincident 85 with the center *a* to a position on the other side of the center *a*. The path of the center *c* is shown in Figs. 8, 9 and 10 by the curved line consisting of dashes and dots and it will be readily seen that this path is a circle 90 drawn with the center *b* as a center, the radius being the distance between *a* and *b*. It should also be noted that while the center *c* always remains in the diametrical line drawn on the circular plate 325 parallel to 95 the sides of the slot 328, yet that, in passing through its position of coincidence with the center *a*, the said center *c* by the act of passing through the center *a* changes its angular position with reference to any point on the 100 said diametrical line 180° degrees as reckoned from the said center *a*; this is clearly seen by a comparison of Figs. 8 and 10, where in Fig. 8 the center *c* is to the right of the center *a* and in Fig. 10 it is to the left. 105 Since the center *c* is the center of the real crank, it is, therefore, readily seen that in the adjustment of the stroke of the crank, the crank instantaneously shifts its angular position with reference to the circular plate 110 325 when the said crank passes through the position of zero stroke, and since the main valve 56 is rigidly connected to the plate 325 this shifting of the said crank with reference to the said plate is also a shifting of the 115 crank with reference to the main valve 56.

In order to keep the scale of the drawings as large as possible the motor which utilizes the fluid pressure generated in the pump is not shown on the same sheet, but 120 both its fluid connections and mechanical connections to the pump are shown as broken off on the right hand end of the pump in Fig. 1.

The motor, a central longitudinal section 125 of which is shown in Fig. 2, is here represented as a partial duplicate of the pump so far as the latter has been described, the parts of it which are similar to those in the pump and designated by corresponding numerals 130

with an accent, the cylinder 31' of the motor corresponding to the cylinder 31 of the pump and similarly for the pistons, connecting rods, crank shaft, valve, etc. In the motor, however, the crank is shown as of fixed length of stroke, the crank pin 41' being formed integral with the crank shaft 40', and the annular rings 53' and 54', which maintain the pitman rods 44', 45' and 46' in contact with the crank pin 41' are fastened to the said crank pin 41' by the screws 353'. The pipe 62' which conveys fluid to the motor is connected to the outlet or pressure pipe 62 of the pump and the pipe 60' which conveys fluid from the motor is similarly connected to the inlet pipe 60 of the pump, so that fluid under pressure may be delivered from the pump to cause the motor to revolve and fluid which is forced out of the motor cylinders as its pistons perform their outward stroke is returned to the pump, the fluid thus being circulated from the pump to motor in repeated cycle. While I have shown the motor as a practical duplicate of the pump except for the adjusting mechanism for varying the length of stroke, it is to be understood that I do not limit myself to any particular type of motor, but prefer the type shown.

In the previous description of the pump the eccentric bush 43 has been described as being provided with a bore by means of which it is mounted on the crank pin 41 and it has been shown that where the eccentricity of the bore of the bush with reference to its exterior circumference is made equal to the eccentricity of the crank pin with respect to the crank shaft, by turning the eccentric bush on the crank pin, the eccentricity of the exterior circumference of the bush with respect to the crank shaft may be made anything between twice the eccentricity of the pin with respect to the shaft, and zero. In the first case the eccentricities are added together and in the latter case they exactly neutralize each other, and in between these limits the eccentricity of the outer circumference of the eccentric bush is an exact function of the angular distance between the center line joining the center of the crank pin to the center of the crank shaft and the center line joining the center of the outer circumference of the bush to the center of its eccentric bore.

In order to angularly adjust the eccentric bush on the crank pin while the latter is in motion and to hold it in whatever position it has been adjusted, the following means are provided: Mounted on the crank shaft 40, Figs. 1 and 4, is a sleeve 77 journaled in a bearing 38, between which sleeve and the crank shaft is inserted a tubular bushing 78. The sleeve 77 terminates at its right hand end in an integral circular plate 79 provided with a diametrical slot 80,

Formed in the adjoining end of the eccentric bush 43 and in its integral annular ring 53 is a diametrical slot 81 similar and at right angles to the slot 80 in the plate 79; this slot 81 is formed centrally with respect to the bore of the eccentric bush and perpendicularly to the line which joins the center of the bore to the center of the periphery of the bush. Interposed between the plate 79 and the eccentric bush 43 is a circular plate 82 provided with a tongue 83, fitting into, and free to slide in, the slot 80, while on the opposite face of the said plate 82 and at right angles to the said tongue 83 is a tongue 84, fitting into, and free to slide in, the slot 81 in the end of the eccentric bush, the said arrangement of tongues, slots and plates constituting what is popularly known as an Oldham coupling which is a well known means for connecting two parallel shafts in different planes. Mounted on the crank shaft 40 at the other end of the sleeve 77 is the adjusting device which effects the movement of the eccentric bush on the crank pin, and which will now be described.

Referring to Figs. 1, 11, 12, 13, 14, 15, 16, 17, 28 and 29, 90 designates a circular plate in each face of which are formed two circular grooves, an inner groove 91 and an outer groove 92 in one face, while in the opposite face is an inner groove 93 and an outer groove 94, the said plate being fastened to the crank shaft 40 by means of a key 95, Fig. 15. Loosely mounted on the crank shaft 40 between the plate 90 and the sleeve 77 is a circular plate 96, terminating on one side in a boss 355 by means of which it is connected to the sleeve 77 by a pin 97, and terminating on the other side in an annular ring 356 which surrounds and projects beyond the said plate 90. Formed in the interior face of the plate 96 is an inner circular groove 98 matching the groove 93 and an outer circular groove 99 matching the groove 94. Mounted in the interior of the annular ring 356 in which the plate 96 terminates is a circular plate 100 in one face of which is formed an inner circular groove 101 matching the groove 91 and an outer circular groove 102 matching the groove 92, the above described grooves being each shown as semi-circular in section whereby each pair forms a circular channel. Mounted in the circular groove 101 is a piston 103 which projects into the groove 91, while facing this piston and mounted in the groove 91 is a piston 104 which projects into the groove 101, the piston 103 being fastened to the circular plate 100 by a pin 105 while the piston 104 is fastened to the plate 90 by a pin 106. Fastened into the outer groove 102 by a pin 107 is a piston 108 which projects into the groove 92, while fastened in the groove 92 by a pin 109 is a piston 110 which projects into the groove 102, the pist

ton 110 being diametrically opposite the piston 104 and the piston 108 being diametrically opposite the piston 103. Fastened in the groove 98 of the plate 96 by a pin 111 is 5 a piston 112 which projects into the groove 93 of the plate 90 and fastened in the groove 93 by a pin 113 is a piston 114 which projects into the groove 98, while fastened in the groove 99 by a pin 115 is a piston 10 116 which projects into the groove 94 and fastened into the groove 94 by a pin 117 is a piston 118 which projects into the groove 99, the said piston 116 being diametrically opposite the piston 112 and the piston 118 15 being diametrically opposite the piston 114. The plate 100 is fastened into the annular ring 356 of the plate 96 by means of a pin 119 and the nuts 120 and 121 which are threaded into the said annular ring. Fastened to the crank shaft 40 by the pin 122 is 20 a circular plate 123 which terminates in an annular ring 124, projecting over and surrounding the annular ring 356 of the plate 96. Formed in the outer circumference of 25 the annular ring 356, diametrically opposite each other, are two longitudinal slots 125 and 126, Fig. 12, extending partially through the body of the ring. Formed in the circumference of the annular ring 124 30 are two diametrically opposite spiral slots 127 and 128, extending entirely through the body of the annular ring, and mounted in the longitudinal slot 125 is a block 129 on the outer face of which is formed a pin 130, 35 passing through the spiral slot 128 in the annular ring 124. Similarly, in the slot 126 is a block 131 on the outer face of which is a pin 132, projecting through the spiral slot 127 in the annular ring 124. Slidably 40 mounted on the ring 124 is a ring 133 on which is a shoulder 134 and mounted on this ring is a second ring 135 which is secured thereto by means of the pins 130 and 132, passing through the spiral slots in the annular ring 124. Mounted on the ring 133, and 45 between the shoulder 134 and the ring 135, is a ring 136, for convenience here called the "yoke," which is shown as slightly larger than the ring 133 for reasons hereinafter described, in which ring 136 are two holes 137 and 138, diametrically opposite each other in which are mounted pins 139 and 140, respectively, the said pins serving to connect the ring-like lever 141 to the yoke 136. At 50 its lower end the lever 141 terminates in a hollow lug 142 in which is mounted a block 145, secured thereto by the pins 143 and 144, which block 145 is also secured to a control rod 146 between shoulders 147 and 148, while 55 the rod 146 is slidably mounted on one side in a bushing 149, Fig. 1, fastened into the casing 150, and, on the other side, in a bore 151 formed in a boss 152, projecting from the crank chamber 34. The upper end of 60 the lever 141 is similarly connected to the 65

valve rod 153, provision for a slight vertical movement of the block 154 between the shoulders of the valve rod 153 being made. From the above description it will be readily seen that if the fluid pressure is admitted 70 between the proper heads of the pistons mounted in the circular grooves in the plates 96, 90 and 100 such fluid pressure will cause the plates 96 and 100 to be rotated with reference to the plate 90, the extent of such rotation being dependent on the amount of fluid admitted, and since the plates 96 and 100 are connected to the eccentric bush 43 by means of the sleeve 77, the pin 97 and the Oldham coupling and the plate 90 is connected to the crank shaft 40 by the key 95, such rotation of the plates 96 and 100, with reference to the plate 90, will cause the eccentric bush 43 to be rotated around on the crank pin 41, and in order, therefore, to 80 utilize this mechanism to perform adjustments of said eccentric bush, it is only necessary to provide means for permitting part of the fluid pressure generated in the pump to pass into the circular channels just 85 described in order to cause the power of the pump to effect the adjustment of its stroke. The further provision of means for controlling the admission of fluid from the pump into the adjusting mechanism and from the 90 adjusting mechanism back into the pump furnishes means for properly controlling the said adjusting mechanism. The means by which this fluid pressure is admitted under proper control to the said circular channels 95 100 to operate this adjusting mechanism will be later described. If all the ports and passages and the cylinders of the pump and the motor and the pipes connecting them are completely 105 filled with a practically incompressible fluid, such as oil or water, and there was no leakage, after these spaces had once been filled it would not be necessary to supply further fluid to the fluid connection, but 110 since practical considerations make it necessary that there be a certain amount of leakage especially around the pistons and valves into the interior of the crank chambers, I find it advantageous to use a small leakage 115 pump which picks up the fluid leaking into the crank chamber and returns it to the fluid connection between the pump and motor. At the left hand end of Fig. 1 is shown such a pump 240, which may be of any form 120 desired but is here shown as of the conventional gear type and supported from the hub 175 by the brackets 241, which are secured thereto by screws 242; the pump is driven by the shaft 40 through the key 243, 125 and a pipe 244, here shown as broken, is connected at one end to the suction side of the said gear pump, its other end being connected to the interior of the casing 150, and enters the casing at the bottom through a 130

plug 245. Connected to the delivery side of the gear pump 240 is a pipe 246, communicating through a pipe 247 with a pipe 248. Formed on the lower side of the pipe 247 is a chamber 249, closed by a cap 250, communication between the pipe 247 and the chamber 249 being normally prevented by the valve 251 held in place by a spring 252. Connected to the side of the chamber 249 is a pipe 253, the other end of which is connected with the interior of the casing 150. Formed on the upper part of the casing 150, as viewed in Fig. 1, are three valve chambers which with their valves and connections constitute the means by which fluid pressure from the pump is utilized to operate the adjusting device for varying the stroke of the pump, and also the means for insuring that the leakage pump will keep the main circuit full of fluid. Of these three valve chambers, the lower one 160 parallel to the axis of the crank shaft 40 is designated the "adjusting valve chamber," the upper left hand one 254 is designated the "circuit valve chamber" and the upper right hand one 255, the "pump valve chamber." In Fig. 1 it will be clearly seen that the pipe 248 is connected to the boss 256 on the side of the said pump valve chamber 255. Connected to the boss 257 on the side of the circuit valve chamber 254 is a pipe 260, the other end of which is connected with the main circuit pipe 62. Behind the boss 257, as viewed in Fig. 1, is a boss 259, see Fig. 20, to which is connected the pipe 258, the other end of which is connected to the main circuit pipe 60. It will thus be seen that the leakage pump is directly connected to the pump valve chamber and that the circuit valve chamber is directly connected to both sides of the main circuit through which the fluid circulates between the pump and the motor.

Slidably mounted in the adjusting valve chamber 160 is the adjusting valve 161, shown more clearly in the longitudinal sectional view in Fig. 20, where it will be seen that said valve terminates at its left hand end in a valve stem 153, by which it is connected to the adjusting yoke 141, as previously described, the block 154 being held between the shoulder 162 and the tubular bushing 163, held in place on the valve rod or stem 153 by a nut 164, so as to prevent longitudinal motion of the block 154 on the rod 153, but to permit a slight vertical motion with reference thereto by reason of the clearance between the said block 154 and the rod 153, Fig. 20. The valve 161 comprises valve heads 165, 166, 167, 168 and 169, and in the valve chamber 160 are ports 170 and 171 here shown as covered by the valve heads 166 and 167, respectively, between which two ports is a port 172.

Referring now more particularly to Fig. 18, Sheet 8, the crank shaft 40 has a bearing in a bushing 176, a split collar 177 with its inclosing ring 178 preventing longitudinal motion of the shaft 40 toward the left. Tightly mounted on the exterior of the shaft is a bushing 179, the right hand end of which adjoins the end of the bushing 176. The hub 175 is counterbored, and fastened against the end of the bore by pins 180 is a ring 181. Surrounding one-half the length of the bushing 179 is a bushing 182 having a collar 183 which fits against the ring 181, while fitting against this collar is a ring 184 mounted in the bore of the hub 175. Surrounding the other half of the bushing 179 is a bushing 185 having a collar 186 fitting against the ring 184, and fitted against the opposite side of the collar 186 is a bushing 187, mounted in the bore of the hub 175. The bushing 187 terminates in a threaded ring 188, whose threads fit threads formed in the interior of a ring 189, secured by suitable means, to the end of the hub 175. Formed in the interior of the ring 189 at its outer end are screw threads into which is fitted a ring 190 and in the outer end of the said ring 190 is a soft washer 191, serving to prevent dust from entering the bearing. Mounted in groove 192 in the shaft 40 is a split ring 193 with its inclosing ring 194, acting as a thrust collar to prevent longitudinal motion of the said shaft 40. Mounted in the bushing 187 is a bushing 195 in which the shaft 40 is journaled. Formed in the shaft 40 near its center and parallel to the axis thereof are two channels 200 and 201, respectively, the channel 201 being connected by the approximately radial holes 202 through the shaft 40 and the bushing 179 with the radial holes 203 through the collar 183 of the bushing 182, the said bushing 182 being provided with a counter bore 204, the width of which, for reasons hereinafter explained, is made equal to the width of the said collar 183, the said counter-bore maintaining the said holes 202 and 203 at all times in communication even when the shaft is rotating. Similarly, the channel 200 in the shaft 40 is connected by means of the radial holes 205 and the counter bore 206 with the radial holes 207 through the collar 186 of the bushing 185. Formed in the hub 175 is a channel 208 the upper end of which is not shown, but which passes through the wall of the casing 150 up to the adjusting valve chamber 160, Figs. 1 and 20, and is there connected to the port 170, thereby connecting said port 170 through the radial holes 203 and 202 with the channel 201 of the shaft 40. In a similar manner, the channel 209 formed in the hub 175 and the casing 150, the upper end of which is not shown, passes up through the wall of the said casing into the port 171 of the adjacent valve chamber 160, see Figs. 1 and 20, and there connects the

port 171 of the adjusting valve-chamber 160 with the radial holes 207 and thence through the radial holes 205 in the shaft 40 to the channel 200. Referring now more particularly to Figs. 1, 15, 16 and 17 the channel 200 is connected by the approximately radial holes 210 and 211 in the shaft 40 with the approximately radial holes 212 and 213, respectively, in the circular plate 90 which, as previously described, is fastened to the shaft 40 by the key 95. The radial hole 212 finally connects through the axial hole 214 with the two outer circular grooves formed in the faces of the circular plate 90, the said axial hole 214 entering the groove 92 between the piston heads 110 and 108 on one side of the circular plate 90 and entering the other circular groove 94 between the piston heads 116 and 118. The radial hole 213 is connected by the axial hole 215 with the inner circular groove 91 between the piston heads 103 and 104, on one side of the plate 90, and on the other side thereof the said axial hole 215 connects with the inner circular groove 93 between the piston heads 112 and 114. In a similar manner the channel 201 is connected through the radial holes 216, 217, and the axial hole 218 with the outer circular channels 92 and 94 at a point just beyond the respective piston heads 110 and 118, and through the radial holes 220, and 221 and the axial hole 222 with the inner circular grooves 91 and 93 at a point just beyond the outer ends of the respective piston heads 104 and 114. If the port 172 in the adjusting valve chamber 160 is connected with a source of fluid pressure supply and the ports 226 and 227 are connected to some chamber into which they can exhaust fluid, it will be readily seen that if the adjusting valve 161 is moved toward the right in Fig. 20 to a sufficient extent to uncover the port 171, fluid pressure will pass into the port 171 thence through the channel 209 formed in the casing 150, thence through the radial holes 207 and 205 into the channel 200 in the shaft 40 (Fig. 18) and thence through the radial holes 210 and 212 and the axial hole 214 into the circular groove 92 between the piston heads 108 and 110, and between the piston heads 116 and 118 in the groove 94, and at the same time fluid will also pass through the radial holes 211 and 213 and the axial hole 215 into the inner circular grooves 91 and 93 between their respective piston heads 104 and 103 in the circular groove 91, and 112 and 114 in the circular groove 93. Fluid pressure thus being permitted to pass between the piston heads 100 will cause the circular plates 96 and 100 which are fastened together to be rotated in a counter clockwise direction, as viewed from the left hand end of Fig. 1, and such rotation of the said plates by their connection through the pin 97, sleeve 77 and the Old-

ham coupling will cause the eccentric bush 43 to be rotated in a counter clockwise direction on the crank pin 41. If there be fluid in the inner circular channels between the outer ends of the pistons 103 and 104 and the pistons 112 and 114, or in the outer circular channels between the outer ends of the pistons 108 and 110 and the outer ends of the pistons 116 and 118, an amount of fluid will pass out of each circular channel, through its connection with the axial channel 201 in the shaft 40, equal in volume to that admitted under pressure between the inner ends of the pistons in their respective circular channels and the fluid so passed into the axial channel 201 will be free to pass through the radial holes 202, 203, and the channel 208 formed in the casing 150 into the port 170, and since at the same time the head 167 of the adjusting valve 161 uncovered the port 171 and thereby connected it to the port 172, the port 170 was uncovered by the head 166 and thereby connected with the port 226, such fluid so passed to the port 170 will be free to pass through the port 226 and into any receptacle provided therefor. In a similar manner, if the adjusting valve 161 is adjusted to the left in Fig. 20 so that the port 172 is connected to the port 170, fluid under pressure will pass in the opposite direction into the circular channels of the adjusting device and thereby cause the eccentric bush 43 to be adjusted in the opposite or clockwise direction as viewed from the left hand end of Fig. 1. In Figs. 1, 11-17 the adjusting mechanism is shown with the pistons at the extreme limit of their clockwise direction of adjustment, so that clockwise adjustments are only made when they have been displaced by counter clockwise adjustments from the positions shown.

It is furthermore evident that, if the adjusting valve 161 is adjusted toward the right in Fig. 20, whereby fluid pressure causes the circular plate 96 to be adjusted in a counter clockwise direction, as viewed from the left hand end of Fig. 1, the ring 133 mounted on the exterior of the annular ring 124 will, through the plate 129 and its pin 130 co-acting with the axial slot 125 in the periphery of the annular ring 96 and the co-acting spiral slot 128 in the ring 124 and the similar co-acting and corresponding parts diametrically opposite thereto, cause the said ring 133 to be displaced toward the left and to an extent depending on the pitch of the spirals 127 and 128 and the extent of the angular counter-clockwise motion of the said adjusting device. Such motion of the ring 133 will cause the yoke 136 to correspondingly move toward the left, and thus the yoke 136 will, through its connection with the adjusting lever 141 cause the adjusting valve 161 to be moved toward the

left, the lower end of the said adjusting lever 141 which is connected to the control rod 146 being supposedly held by the operator and prevented from longitudinal motion. Since the counter-clockwise adjustment of the adjusting device was produced by the adjusting valve being adjusted to the right in Figs. 1 and 20 and since such counter-clockwise motion of the adjusting device caused the adjusting lever to move the adjusting valve toward the left and since inverse adjustments of the adjusting valve will cause the adjusting device to so move the adjusting lever as to cause the adjusting valve to be replaced in its normal or neutral position where the ports 170 and 171 are both covered by their respective valve heads and since, by manual adjustment of the rod 146 the adjusting lever 141 pivoted to the yoke 136 by the pins 138 and 139, and the adjusting valve 161 can be adjusted in either direction and the adjusting mechanism thereby caused to adjust the eccentric bush 43 in a corresponding direction and to a corresponding amount till the motion of the adjusting mechanism has caused the adjusting valve 161 to be replaced to its normal or neutral position, and it is obvious that such a combination of mechanism provides means for causing fluid pressure to adjust the eccentric bush 43 and thereby to vary the throw of the crank of the pump to an extent determined by the extent of the manual adjustment of the said rod 146. It is to be particularly noted that the above described mechanisms not only cause the stroke of the crank to be adjusted simultaneously with and to an extent corresponding to the manual adjustments of the rod 146, but that as soon as the said mechanisms have effected such adjustments of the stroke of the pump crank they act to lock the stroke at the point arrived at, since any extraneous movement of the eccentric bush after the adjusting valve 161 has been returned to its neutral position would involve the impossible function of forcing fluid through ports and passages which have been closed by the said adjusting valve.

In the foregoing description of the adjusting mechanism it has been assumed for simplicity that a source of fluid-pressure supply was connected to the port 172 and that the fluid exhausted from the adjusting mechanism was free to pass out of the ports 226 and 227 into some receptacle provided therefor; since, however, the pump itself is capable of furnishing a fluid pressure supply for operating the adjusting mechanism I provide means for properly securing this fluid pressure supply for the adjusting mechanism from the pump itself, such means consisting, in the present instance, of the three valve chambers 160, 254 and 255 and their valves and connections previously referred to. Referring now more particularly to Figs. 20, 21, and 22, from a detail illustration of these means, it will be seen that a circuit valve 261 comprising three heads 262, 263 and 264, is slidably mounted 70 in the valve chamber 254.

Closing the left hand end of the valve chamber 254 is a recessed plug 265 in which is mounted a stop-rod 266, adjustably secured to the said plug by threads 267 and a 75 nut 268 and extending a considerable distance into the valve chamber and passing into a hole 269 in the stem of the said valve 261. The head 262 is counter-bored to receive a compression spring 270, confined between the said head 262 and the plug 265, which normally pushes the valve 261 toward the right and against a stop 275 on a plug 276 closing that end of the valve chamber. Mounted in the pump valve chamber 255 is a 80 pump valve 271 comprising three heads 272, 273 and 274, respectively. Closing the left hand end of the pump valve chamber 255 is a plug 277 in which is mounted a stop-rod 278 adjustably secured to the said plug 85 by screw threads 279 and a nut 280. Surrounding the rod 278 is a compression spring 281, confined between the valve head 272 and the plug 277, and normally causing the pump valve 271 to be forced to the right till the 90 head 274 is against the stop 282 on the plug 283, closing that end of said valve chamber. Formed in the circuit valve chamber 254 is a port 285 connecting with the boss 257, with which the pipe 260 is connected as 95 previously described. Formed in the same valve chamber 254 is a similar port 286 connecting through the boss 259 with the pipe 258 previously described, the pipe 258 thus connecting the valve chamber 254 with one 100 side of the main fluid circuit and the pipe 260 connecting it with the other side thereof. Leading from the port 285 is a small channel 287 which connects with the port 288 in the left hand end of the circuit valve chamber 110 254, a similar channel 289 on the right hand side connecting the port 286 with the port 290. Mid-way the length of the circuit valve chamber 254 is a narrow port 291, which, by means of the channel 292, is connected with the port 293 in the extreme right hand end of the pump valve chamber 255. In the right hand end of the circuit valve chamber 254 is a port 294, and in a symmetrical position in the left hand end is a 115 120 corresponding port 295, connected together by a channel 296, more clearly seen in Fig. 22.

In the pump valve chamber 255 near the right hand end is a port 297, connected by a suitable channel, not shown, with the high pressure supply port 172 in the adjusting valve chamber 160, the said channel which connects the port 297 with the port 172 being formed in the lower side wall of the said valve chamber 255. Near the port 300 in 125 130

the pump valve chamber 255 is a port 298, connected by a channel 303 with the port 299 of the adjusting valve chamber 160, the said channel 303, formed in the side wall 5 of the adjusting valve chamber 160 and passing along the same till it reaches the pump valve chamber 255, when it makes a right-angle bend and passes along the bottom side wall of the said valve chamber 255 till 10 it reaches the said port 298, which it enters, and port 299 being shown in dotted outline in Fig. 21 and the said port 299 being shown in Fig. 20 as a dotted circle. Adjoining the port 298 in the pump valve chamber 255 is 15 a port 300, which connects through the boss 256 with the pipe 248, and thence with the delivery side of the leakage gear pump 240, previously described. Adjoining the port 300, on the other side from the port 298, 20 is a port 301 which connects through the channel 302 with the channel 296, which connects the port 294 to the port 295, and, during this course, crosses the chamber 160 through which it passes at the port 226, and 25 thence finally by means of the channel 303 with the ports 294 and 295 of the circuit valve chamber 254 and with the ports 226 and 227 of the adjusting valve chamber 160. It will be noted that the port 226 is formed 30 by the intersection of passage 296 with the bore of adjusting valve casing 160, and passage 306 connects port 227 in the casing 160 with passage 296 and hence with the bore of casing 160 at the so-called port 226.

35 In the stem connecting the pump valve heads 272 and 273 is a radial hole 304 connecting through an axial hole 325 in the said valve with the radial holes 305, in the stem between the valve heads 273 and 274.

40 In Fig. 22 the middle circle, situated between the channel 306 and the channel 302 represents the bore of the adjusting valve chamber 160 which, it should be remembered, lies in a plane below and with its 45 axis perpendicular to the axes of the circuit valve and pump valve. Closing the right hand end of the adjusting valve chamber 160, Fig. 20, is a plug 307. In the upper portion of the casing 150, Fig. 22, is a small 50 chamber 309, normally closed against the channel 296 by a valve 310 held in place by the spring 311, which, for reasons herein-after explained, is so adjusted that the valve opens when the pressure in the chamber 296 55 rises to some predetermined amount above atmospheric pressure. The stem of the valve 310 is guided by a gland 312 in which are formed holes 313 to permit fluid to pass from the chamber 309 into the interior of 60 the casing 150. Leading from the port 299 in the right hand end of the adjusting valve chamber 160 and between the heads 168 and 169 is a channel 314, Fig. 21, which connects with the channel 306, as previously ex- 65 plained, connecting with the channel 296

and thereby with either the port 285 or the port 286, depending on the position of the circuit valve 261.

This system of valves just described is so interconnected through the channels and 70 ports that the circuit valve 261 will, when pressure exists in the main circuit between the pump and the motor, maintain a supply of fluid pressure in the port 172 of the adjusting valve and at the same time maintain 75 a connection between the ports 226 and 227 of the adjusting valve and the low pressure side of the main fluid circuit. When there is no supply of fluid under pressure in the main fluid circuit between the pump and 80 the motor, as when the pump crank has been adjusted to zero stroke, the pump valve 271 will automatically shift to such a position 85 as to enable the port 172 to be supplied from the leakage pump 240, with fluid under 90 pressure to operate, should the operator so desire it, the adjusting mechanism sufficiently to adjust the pump crank from zero to a position where it has stroke and therefore where there is again pressure 95 in one side or the other of the main fluid circuit.

Referring to Figs. 1, 3 and 25, it will be seen that in the head of piston 50 there is a hole 360, in which is slidably mounted a 95 tube 361, terminating at its lower end in a crescent shape shoe 362, which fits around and bears on the rounded end of the pitman rod 44; the bore 363 of this tube 361 terminates at its lower end in a recess 364. 100 Drilled through the pitman rod 44 from end to end is a hole 365, connecting, at its upper end, with the recess 364 in the shoe 362, the said hole 365 terminating at its lower end in a recess 366 formed in the bearing 105 surface of the pitman rod 44 where it bears on the exterior of the eccentric bush 43. Formed in the bore in the upper end of the pitman rod through which the piston pin 17 passes, is a counterbored groove 110 367, connecting together the two portions of the hole 365 where it is interrupted by the pin 47. It will be seen from Fig. 25 that the recess 366 in the bearing surface of the pitman rod 44 is entirely surrounded 115 by a groove 368, and this groove 368 is connected to the outer periphery of the bearing surface by the several grooves 369. The area of the recess 366 projected onto a plane perpendicular to the length of the pitman 120 rod 44, is preferably made equal to a considerable fraction of the area of the piston 50, and the projected area which is inclosed by the surrounding groove 368 is preferably made just equal to or slightly less than the 125 area of the piston 50, for, when such is the case, a slight amount of the fluid pressure generated in the pump cylinder 31 will be free to pass through the tube 361, pitman rod 44 and into the recess 366, where it will 130

spread out over the area of the recess 366, and thereby relieve the bearing surface of the pitman rod 44, where it bears on the eccentric bush 43, of a certain portion of the bearing pressure due to the fluid pressure acting on top of the piston 50, the percentage by which this bearing pressure is relieved being an exact function of the projected area of the recess 366, for if the recess 366 were exactly equal to the area of the piston 50 the pressure between the bearing surface of the pitman rod 44 and the eccentric bush 43 would be exactly counterbalanced by the fluid pressure in the recess 366, and while there would still be a pressure on the eccentric bush exactly equal to the pressure due to the area of the piston 50, this pressure would be purely fluid pressure acting on the bush 43, and since the friction between the fluid and the bush 43 is only a minute fraction of what it would be between the pitman rod and the bush, it is readily seen that the friction of the mechanism will be greatly reduced. I prefer, however, not to make the recess 366 quite equal in area to the area of the piston 50, since it is necessary to have some locking surface around the recess 366 the fluid pressure penetrates to a certain extent between this surface and the surface of the bush 43, and thereby tends to lift the pitman rod from its bearing, and thus permit fluid pressure to leak out of the recess. I, therefore, make the projected area of the recess 366 a considerable fraction of the area of the piston, so that the pressure between the bearing surface of the pitman rod and the eccentric bush is not entirely counterbalanced, the pressure which is not counterbalanced thereby holding the surface of the pitman rod tightly against the surface of the eccentric bush and preventing fluid from leaking between these surfaces. Since, however, between any two surfaces fluid pressure will penetrate to an extent depending on the accuracy with which the surfaces fit each other and the extent of the pressure to which they are subjected, I surround this recess 366 with the groove 368, which, as stated before, incloses an area which, when projected on a surface perpendicular to the pitman rod is equal to or just less than the area of the piston 50, so that even though there be penetration of the fluid between the surfaces it will not be able to act on a surface greater in area than the area of the piston, thereby preventing the pitman rod from being raised from the bush and thus preventing leakage of the fluid pressure from the recess 366, the fluid pressure which penetrates between the surfaces and into the surrounding groove 368 being carried from between the bearing surfaces through the several grooves 369.

In Fig. 3 it will be clearly seen that the

shoe 362 in which the tube 361 terminates is pressed against the exterior surface of the pitman rod 44 by the fluid pressure acting on the upper end of the said tube 361; the extent of the pressure between the shoe and the pitman rod being dependent on the area of the recess 364 relative to the area of the end of the rod 361, the area of this recess being preferably made slightly less than the area of the end of the rod, as is shown in Fig. 26, which is a plan view of the surface of the shoe 362 where the same rubs on the exterior surface of the end of the pitman rod 44; this recess is surrounded by a small groove 370 and the projected area enclosed by the groove 370 is equal to or slightly less than the area of the upper end of the tube 361, and such fluid as penetrates through the locking surface between the recess 364 and its surrounding groove 370 is carried from between the surfaces by the grooves 371, thereby preventing the shoe 362 from being raised from contact with the end of the pitman rod and thus preventing leakage. While the main object of thus conveying fluid pressure between the bearing surface of the pitman rod on the eccentric bush is to relieve the metallic bearing surfaces of a large portion of their bearing pressure, yet when the fluid in the main fluid circuit between the pump and the motor is oil or some other fluid possessing lubricating qualities, a further very great advantage is also incidentally obtained in that the bearing surfaces which are subjected to the unbalanced pressure and which act as locking surfaces to prevent leakage of the fluid, work under very advantageous conditions as regards lubrication; for, when the fluid pressure is high and the unbalanced bearing pressure, therefore, correspondingly high, the fluid penetrates to a greater or less extent between the surfaces and thereby assists very greatly in the proper lubrication of these bearing surfaces. All of the other pistons and pitman rods are similarly equipped with the above described means of conveying fluid pressure between the pitman rods and the eccentric bush. Similarly in the motor, shown in Fig. 2, corresponding parts and passages convey fluid pressure between the several pitman rods and the crank pin 41', and thereby greatly reduce the friction between the bearing surfaces of the pitman rods and the said crank pin 41'.

The bearings 38 and 39 of the pump have formed in them the small holes 373 permitting fluid to pass from one end to the other of the crank chamber 34, and the corresponding bearings 38' and 39' of the motor are similarly provided with the holes 373', and the interior of the crank chamber 34 of the pump is connected to the interior of the crank chamber 34' of the motor by a pipe 374, whereby fluid leaking into the crank

chamber 34' is free to pass therefrom into the crank chamber 34, and thence into the casing 150 of the pump whence it is sucked by the leakage pump 240 through the pipe 244 and returned to the main fluid circuit as heretofore explained.

The crank shaft 40 is extended beyond the right hand end of the crank chamber 34, Fig. 1, and this end of the crank chamber is closed by a cap 375 secured thereto by the screws 376. On the right hand end of the crank shaft 40, one-half of a clutch 379 is slidably secured by means of a key 377 engaging a key-way 378, in the face of which 15 clutch member are formed tongues 380 and grooves 381. The other member or hub 384 of the clutch 379 has formed in it a counter-bore 383 in the end of which is mounted a cup packing 382. Secured upon the shaft 20 40 by a pin 385 is a collar 386, in the right hand face of which is mounted a similar cup packing 387, facing the cup packing 382. Secured to the end of the hub 379 by screw threads is a cap 389 between which 25 cap and the collar 386 is a compression spring 390 which forces the clutch 379 toward the left. In the shaft 40, parallel to its axis, is a channel 391, connected by means of radial hole 392 with the space between 30 the cup packings 382 and 387. The channel 391 connects at its other end with the radial hole 393 located in the shaft where the circular plate 96 of the adjusting device bears thereon. In the inner circular groove 98 35 of the circular plate 96 is a radial hole 394, Fig. 16, which, in the position shown in said figure, is in line and connects with the radial hole 393 in the shaft 40. In the interior of the bore of the circular plate 96, where it 40 bears on the shaft 40, is a crescent shaped exhaust groove 395 extending circumferentially around from a point just beyond the radial hole 394 to a point a short distance from the other side of the radial hole 394. 45 As previously stated, the radial hole 393 connects with the radial hole 394. It is evident from the construction shown in Fig. 16 that, when the circular plate 96 is adjusted in a counter-clockwise direction with 50 reference to the shaft 40, the radial hole 393 connects with the crescent shape groove 395. By means of these radial holes, channels and grooves, fluid pressure existing in the inner circular groove 98 will, when the parts are 55 in the positions shown in Fig. 1, pass through these connections into the space between the cup packings 382 and 387 on the right hand end of the shaft 40 and such pressure will cause the clutch 379 to be forced to the right and such forcing of the 60 clutch 379 to the right will cause it to clutch its coacting member 379' rigidly secured to the motor shaft 40', thereby locking together the said pump shaft 40 and motor shaft 40' and thereby causing them to rotate 65

at equal speeds. On the hub 379 is a shoulder 396 and rotatably mounted between the said shoulder and the end of the cap 389 is a collar 397, on which, see Figs. 23, 24 and 27, at diametrically opposite points are two pins 398 having a rocking connection 70 with the forks 399 in which a yoke lever 400 terminates.

On the side of the main circuit pipe 60, and at right angles thereto, is a pipe 401 75 and on the main circuit pipe 62 is a similar pipe 402, which pipes 401 and 402 are connected together through a valve chamber 403, which is provided with a partition 404 separating said valve chamber into two portions 405 and 406, the former connected with the pipe 401 and the latter with the pipe 402. The partition 404 extends into the chamber 405 in the form of two tubular valve seats 407 and 408, in which is mounted 80 a valve 409 embodying two heads 410 and 411, fitting the seats 408 and 407, respectively. Extending from the left hand end of the valve 409, as viewed in Fig. 27, is a stem 422 on the end of which is mounted 85 a nut 423, between which nut and a shoulder 424 is a washer 425, having on its left hand face a yoke 426, terminating in a rod 417, slidably mounted in a cap 428 secured to that end of the valve chamber by screws 90 429 and closing the same, on the end of which rod is a handle 418. Confined between the washer 425 and the valve head 410 is a compression spring 430, and as the yoke 426 is limited in its motion toward 95 the left by the cap 428, the said spring 430 keeps the valve 409 pressed toward the right to the full extent allowed by the nut 423. On the right hand end of the valve 409 is a stem 421 on the end of which is a nut 100 413 between which nut and a shoulder 414 is a washer 415 on which is a yoke 416 on the end of which is a rod 427. This end of the valve chamber is closed by a cap 419 secured thereto by the screws 420, the yoke 105 416 being limited in its motion to the right by the said cap. A spring 412 confined between the washer and the valve head 411 forces the valve 409 to the left to the limit allowed by the nut 413. In the valve head 110 410 are two sets of radial holes 431 and 432, all the holes of 431 being circumferentially in line with each other, and all the holes of 432 being circumferentially in line 115 with each other.

In the tubular valve seat 408 is a row of radial holes 433 which, when the valve is in the position shown, are mid-way between the radial holes 432 and 431, the valve head 410 and the co-acting tubular seat 408 preventing the said radial holes 433 from communicating with either the radial holes 431 or 432 when the valve is in the position shown. In the valve head 411 are two rows of radial holes 434 and 435, respec- 120 125 130

tively, and in its co-acting tubular seat 407 is a row of holes 436, situated with respect to each other similarly to the corresponding holes in the valve head 410. Connected 5 to the end of the rod 427 by the pin 437 is the lever 400, which, as previously described, is connected at its other end, Figs. 23 and 24, through the forks 399 and the pins 398 with the yoke 397 on the clutch 379, the said lever 400 being fulcrumed by a pin 439 to the bracket 438 formed on the side of the valve chamber 403. The valve heads 410 and 411 mounted in their respective tubular seats 408 and 407 normally 10 prevent the pipes 401 and 402 from communicating with each other. It will be noted, however, that the valve head 410 is made larger than the valve head 411, and that therefore if fluid pressure is brought 15 into the chamber 406 the force on the head 410 will be greater than that on the head 411, and will thereby tend to force the valve 409 to the right, in Fig. 27, thereby tending to compress the spring 412. Similarly 20 fluid pressure brought into the chamber 405 through the pipe 401 will act on the two valve heads 410 and 411, and the unbalanced force acting on the head 410 will tend to force the valve 409 toward the left, 25 thereby compressing the spring 430. The springs 412 and 430 are so proportioned with reference to these unbalanced forces tending to displace the valve that the spring 412 does not permit the valve 409 to be 30 moved to the right sufficiently to permit the radial holes 434 in the valve head 411 to communicate with the radial holes 436 in the tubular seat 407 and the radial holes 432 in the valve head 410 to communicate 35 with the radial holes 433 in the tubular seat 408 until the fluid pressure in the chamber 406 has reached some predetermined value. Similarly the spring 430 does not permit the radial holes 435 in the valve head 411 40 to communicate with the radial holes 436 in the tubular seat 407, and the radial holes 431 in the valve head 410 to communicate with the radial holes 433 in the tubular seat 408 until the fluid pressure in the 45 chamber 405 has reached some predetermined pressure, which may be either the same predetermined pressure as before or some other as desired. It is evident, however, that when the radial holes in the valve 50 heads do communicate with the radial holes in the tubular seats, communication is established between the chamber 405 and the chamber 406, thereby establishing communication between the pipes 402 and 401, and 55 when such communication between the said pipes is established they constitute a bypass between the two main circuit pipes 60 and 62. The said valve 409, with the co-acting parts thus described, thus constitutes a safety valve which prevents the 60

fluid pressure in the main fluid circuit from rising above some predetermined point. It is furthermore evident that when the clutch 379 is forced to the right in Fig. 1, so that it locks with the clutch 379', the yoke 397 70 through its pins 398 and the lever 400 causes the valve 409 to be forced to the left, as viewed in Figs. 1, 24 and 27, thereby establishing communication between the pipes 101 and 402, and consequently by-passing 75 the fluid in the main fluid circuit. It should be noted that in connecting the lever 400 to the rod 427 the end 480 of the said lever 400 is provided with a slot 440 through which the pin 437 passes, and that the said 80 slot 440 permits the necessary motion of the lever 400 in a vertical direction. The said slot 440 is of such a width that while the pin 437 is normally in contact with the right hand side of the said slot 440 when 85 the parts are in the positions shown, the clutch 379 is at the extreme limit of its movement toward the left, so that any movement of the clutch toward the right causes the lever 400 to immediately move 90 the valve 409 toward the left; but the rod 427 is free to move toward the left to the full limit of its motion without the pin 437 being brought in contact with the left hand side of the slot 440. By this means, movement 95 of the clutch toward the right causes a corresponding movement of the valve 409 toward the left, but the valve 409 is free to move toward the left when acting as a safety valve, without causing any movement 100 of the said clutch. It is furthermore evident from Fig. 27, that the valve 409 may be displaced toward the right by means of the handle 418 till the radial holes 432 connect with the radial holes 433 and the radial holes 434 connect with the radial holes 436, thereby establishing communication between the two by-pass pipes 401 and 402 without in any way affecting the clutch 379, and therefore the said valve furnishes 105 a means, under manual control if desired, for by-passing the fluid without causing a simultaneous operation of the clutch. It should be noted in Figs. 1, 24 and 27 that the jaws of the co-acting clutches 379 and 379' are so situated with reference to each other that while they are out of contact with each other yet they are sufficiently close so that when they are brought into contact, thereby clutching together the two 110 shafts 40 and 40', they begin to clutch before the lever 400 has moved the valve 409 sufficiently to cause the co-acting radial holes in the valve heads and tubular seats to come into communication, so that 115 the fluid is not automatically by-passed by the clutch until its two members have actually gripped. When the tongues and grooves of the respective clutch members 120 have been forced further into engagement, 125 130

the said lever 400 moves the valve 409 to a position where the radial holes communicate with each other and thereby cause the fluid to be by-passed. It is furthermore 5 evident that if it is desired the lever 400 may be operated by hand either by taking hold of it firmly or by suitable connections therewith, and that thereby the clutch may be operated by manual control instead of 10 fluid pressure admitted from the adjusting device.

The operation of the device is as follows: Assuming all the ports and passages to be filled with fluid and an extra amount of 15 fluid to be in the crank chambers and also in the casing of the pump, and the crank shaft 40 to be driven by some external power and in a clockwise direction as viewed from the left hand of Fig. 1 and 20 all parts to be in the positions there shown, the piston 50 in the cylinder 31 is just starting to make its downward stroke during which it will take in fluid through its port 35, the valve port 57 and the pipe 60, and 25 at the same time the piston 51 will move outward in the cylinder 32 forcing fluid therefrom through its port 36, the valve port 58 and into the pipe 62; the piston 52 in its cylinder 33 has nearly finished its 30 suction stroke, but it will continue to take in fluid through the pipe 60, the valve port 57 and its port 37 until it reaches its inner dead center. The fluid forced out from the cylinder 32 into the pipe 62 will 35 pass over to the pipe 62' of the motor where it will pass through the port of the main circuit valve 56' of the motor corresponding the port 57' on the opposite sides and thence into the cylinder 33' causing the 40 crank pin 41' and consequently the shaft 40', to be rotated in a clockwise direction as viewed from the left hand end of Fig. 2. As soon as the crank pin 41' begins to move, the valve 56', fastened to the shaft 40' by 45 the key 55', of the motor will begin to uncover the port 35' of the cylinder 31' allowing fluid to also pass from the pipe 62' into it where, acting on the piston 50', it will also produce a turning effect on the 50 crank pin 41'. At the same time that the fluid forced over under pressure by the pump to the motor enters the cylinders 33' and 31' and thereby causes the motor crank pin 41' to be revolved, and the piston 55 in the third cylinder not shown will move upward in its cylinder pushing the fluid out of the said cylinder through its port thence into the valve port 57' the pipe 60' and finally into the pipe 60, thereby furnishing 60 a supply of fluid for the said pump cylinders 31 and 33 which are both making their suction strokes, and the total amount of fluid in the cylinder ports and passages will, therefore, be circulated around 65 from the pump to the motor and back to

the pump, the said fluid thereby forming a fluid connection through which the motor is driven by the pump.

As soon as pressure is generated in the main circuit pipe 62 the fluid in the pipe 260 connected thereto is subjected to the same pressure which is thereby conveyed to the circuit valve chamber 254 to which the pipe 260 is connected through the boss 257. Fluid pressure entering the valve chamber 254 through the said boss 257 is free to pass through the port 285 into the port 291 owing to the fact that the spring 270 under normal conditions forces the circuit valve 261 toward the right in Fig. 21, but even if this spring 80 were not in the position shown the fluid pressure which enters through the port 285 would force the valve to the position shown because the channel 287 connects the port 285 to the port 288, whereby pressure existing in 85 the port 285 is conveyed to the left hand end of the said circuit valve 261 where it acts against the head 262 and forces it to move. Fluid pressure thus conveyed to the port 291 passes through the channel 292 and into the port 293 in the right hand end of the pump valve chamber 255 where, if the pump valve 271 were over to the extreme right of the said valve chamber and against the stop 282, the said fluid pressure would 90 force it to the left against the action of the spring 281. The extent to which the pump valve 271 is forced to the left depends on the relative proportions between the stiffness of the spring 281 and the area of the end of the 95 pump valve 271 and the extent of the pressure to which the fluid has been raised by the action of the main pump. Assuming, for illustration, that the spring 281 requires a force of 100 pounds to compress it sufficiently to permit the pump valve 271 to press against the rod 278 which forms a stop beyond which the valve cannot be forced, and assuming that the fluid pressure generated in the main circuit has been sufficient 100 to cause a pressure of 100 pounds against the right hand end of the pump valve 271 the said pump valve will be forced to the left against the stop 278 as represented in Fig. 110 21, thereby permitting the port 293 to connect with the port 297 which, as previously explained, is connected with the port 172 in the adjusting valve chamber 160.

If fluid pressure has been generated in the other side of the main fluid circuit either by 115 revolving the pump shaft 40 in the opposite direction or by adjusting the stroke of the pump through zero to a position where it has shifted with reference to the main valve 56, so that the pipe 60 is the pressure pipe, 120 fluid pressure will then pass through the pipe 258 and the boss 259 into the port 286 of the circuit valve chamber 254 and such fluid pressure so passed to the port 286 will 125 be transmitted through the channel 289 and 130

the port 290 to the right hand end of the said valve chamber where, acting against the head 264 of the circuit valve 261, it will force the said valve to the left against the 5 action of the light spring 270 thereby closing the port 294 and causing the head 263 to pass from the right hand side of the port 291 to the left hand side thereof and thereby connecting the port 291 to the said port 286 10 and such fluid pressure will then pass through the port 291, the channel 292 and the port 293 in the right hand end of the pump valve chamber 255, where its action on the pump valve will be the same as that 15 just previously described as the case when the fluid pressure was generated on the other side of the main fluid circuit and conveyed to the circuit valve chamber through the port 285. It is, therefore, evident that 20 the port 172 in the adjusting valve chamber 160 will, through its connection with the port 297, be maintained in connection with the high pressure side of the main circuit no matter which side happens at the moment 25 to be the high pressure side. As previously described, the leakage pump, by means of the pipes 246, 247 and 248 and the boss 256, is directly connected through the port 300 with the pump valve chamber 255. When the 30 pump valve has been forced to the left in the position shown in the drawing by the fluid pressure from the main fluid circuit acting on the head 274, the port 300 is in direct communication with the port 301 35 which through the channel 302 connects with the channel 296 which, as previously described, not only joins together the two ports 294 and 295 of the circuit valve chamber, but also connects with the port 226 of the 40 adjusting valve chamber and through the channel 306 with the port 227 of the adjusting valve chamber. In Fig. 21 the circuit valve is in the position to which it is forced when fluid pressure is brought into the port 45 285 and it will be seen that the port 294 is uncovered by the valve head 264, and since this port 294 connects with the channel 296 the leakage pump through its connections just described is connected to the port 286 50 and from thence through the pipe 258 with the main pipe 60 which we have supposed to be the low pressure side of the main fluid circuit. When the pressure changes in the main fluid circuit so that pressure is brought 55 into the port 286 by the pipe 258 and the circuit valve 261 is thereby forced to the left, Fig. 21, the port 294 is covered by the valve head 264 and at the same time the port 295 in the other end of the circuit 60 valve chamber is uncovered by the head 262 and is, therefore, permitted to communicate with the port 285 and since the port 300 in the leakage valve chamber is, as previously described, connected to the channel 296 when 65 the pump valve 271 is in the position shown

the said leakage pump is under these conditions connected to the port 285 and through the pipe 260 with the main circuit pipe 62 which for the moment we have assumed to be the low pressure side of the main fluid 70 circuit. Similarly since the ports 226 and 227 are connected with the channel 296 as previously described, the said ports 226 and 227 of the adjusting valve chamber 160 are always connected to the low pressure side of 75 the main fluid circuit no matter which side happens to be the low pressure one. It is, therefore, evident that by the means just described the leakage pump 240 is normally maintained in communication with the low 80 pressure side of the main fluid circuit as are also the ports 226 and 227 of the adjusting valve chamber 160 and that the port 172 of the said adjusting valve chamber is always maintained in communication with the high 85 pressure side of the main fluid circuit. When the leakage pump has raised the pressure in the low pressure side of the main fluid circuit to some predetermined point the valve 310 in the chamber 309, Fig. 22, 90 automatically opens against the spring 311 permitting excess fluid to pass from the channel 296 into the interior of the casing 150, thereby maintaining whatever back pressure is desired in the low pressure side 95 of the main fluid circuit. It may not be at first evident why a back pressure is maintained in the low pressure side of the main fluid circuit for it appears at first as a distinct disadvantage, but I have found from 100 practice that there is a very distinct advantage in maintaining a back pressure slightly above atmospheric pressure in the low pressure side of the main fluid circuit especially in machines working at moderate and high 105 speeds, the back pressure preventing cavitation which otherwise occurs when the pistons in the cylinders move so rapidly that atmospheric pressure is not able to cause the fluid to follow the piston rapidly enough. 110 If the pump and the motor each comprises an equal number of cylinders and the total area of the pistons of the pump equal the total area of the pistons of the motor and their length of strokes be equal, the motor 115 will necessarily have to rotate at the same speed as the pump. If, however, the length of stroke of the pump be reduced to less than that of the motor, the motor will be driven at a speed proportionately less than the 120 speed of the pump. If then while the crank shaft 40 is in rotation, fluid be admitted into the adjusting mechanism of the pump previously described so that the eccentric bush 43 is rotated counter-clockwise from its 125 position shown in Fig. 1 to a position where the outer circumference of the eccentric bush 43 is less eccentric to the shaft 40, it will thereby reduce the length of the stroke of the pump and consequently correspondingly 130

reduce the speed of the motor. To effect such adjustment of the stroke of the pump it is only necessary to move the control rod 146 to the left in Fig. 1, thereby causing the lever 141 to be correspondingly rocked on its pins 138 and 139, pivotally connecting it to the yoke 36, until the upper end of the said lever 141 has caused the adjusting valve 161 to be moved toward the right in Figs. 1 5 and 20 until the head 167 has partly uncovered the port 171, thereby permitting the fluid from the constantly high pressure port 172 to pass into the port 171 and thence through the channel 209 in the casing 150. 10 Fig. 18, the radial holes 207 and 205 and into the channel 200, and thence, Figs. 15 and 17, through the holes 210, 212 and 214 into the outer circular grooves 92 and 94 in the circular plate 90 of the adjusting mechanism, 15 such fluid acting between the pistons 108 and 110 and the pistons 116 and 118, and some of the said fluid also passing through the holes 211, 213 and 215 in to the inner circular channels of the said plate 90 between the piston heads 103 and 104 and 112 and 114; 20 the fluid under pressure which enters the said circular grooves between the said piston heads, thereby causing the circular plates 96 and 100 to be adjusted in a counter clockwise direction until the extent of the 25 said adjustment has been sufficient to cause the pins 130 and 132, Fig. 12, through their connections with the longitudinal slots 125 and 126 and the spiral slots 127 and 128, to move the ring 133 and thereby the yoke 136 30 toward the left in Fig. 1 to an extent sufficient to cause the head 167, Fig. 20, of the said adjusting valve 161 to again cover the port 171. At the same time that fluid under 35 pressure thus acted between the pistons in the circular grooves of the adjusting mechanism to adjust the said eccentric bush around, an equal amount of fluid between the opposite heads of the pistons in the circular 40 grooves of the adjusting mechanism was forced out through their connections with the channel 201 in the shaft 40 and thence, through its connections as previously described with the channel 208 in the casing 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

be caused to adjust the eccentric bush in a counter clockwise direction until the outer periphery of the said bush is brought to the position where it is concentric with the crank shaft 40 when, as previously explained, the length of the real crank has become zero and the pistons in the pump cylinders are, therefore, not reciprocated and consequently motion of the shaft 40 causes no motion of the motor shaft 40'. Such a position of zero stroke is reached when the adjusting mechanism has been adjusted through 180 degrees and thereby caused the eccentric bush to be adjusted through 180 degrees and the eccentric bush in passing through its position of maximum stroke, as shown in the drawings, to the position of zero stroke passes through all lengths of stroke between the said maximum stroke and zero and consequently causes the speed of the motor shaft 40' to be varied between the maximum due to the maximum length of stroke of the pump crank to zero, and since the eccentric bush in its adjustment may be stopped at any point desired by merely ceasing to adjust the control rod 146 to the left, the motor shaft 40' may, therefore, be caused to operate for any desired length of time at any desired speed and may at will be varied from the maximum to zero. 95

When the adjustment of the control rod 146 to the left has been continued to the point where the eccentric bush has been brought to zero stroke further adjustment of the said rod toward the left will cause the eccentric bush to again have stroke, but, as previously explained, in passing through zero the real crank shifts its position through an angle of 180 degrees with reference to the main circuit valve 56 and thereby causes the ports of the said main valve to be exactly reversed, the port which was formerly the high pressure port now becoming the low pressure port and vice versa, and since such a reversal of the said ports of the main valve causes the fluid which is under pressure to be delivered to the main circuit pipe, which formerly conveyed the low pressure fluid, and the low pressure port to be connected to the pipe which formerly conveyed the fluid under high pressure, the fluid pressure is therefore conveyed in the opposite direction to the motor and thereby causes the motor to revolve in the opposite direction and by continuing the adjustment of the control rod 146 to the left the stroke of the pump may be increased to any desired point on this opposite side of the zero point and the motor thereby caused to operate at correspondingly increased speeds in the opposite direction. In a similar manner adjustment of the control lever 146 toward the right in Fig. 1 causes the adjusting mechanism to adjust the eccentric bush 43 in a clockwise direction 130

and thereby, if the center of the real crank is on the reverse side of its zero position, such adjustment of the eccentric bush in such direction will decrease the stroke of the eccentric bush until it reaches the position of zero stroke and further adjustment of the control rod 146 to the right will cause the eccentric bush to be further adjusted in a clockwise direction and the real crank will pass from its position of zero stroke to a length of stroke depending on the said adjustment of the said control rod 146.

In Figs. 1 and 12 I have shown a pin 450 which is fastened in the annular ring 356 of the circular plate 96 and which projects through the interior thereof into a groove 451 formed in, and extending partly around, the outer periphery of the circular plate 90 which is keyed to the shaft 40. With the parts in the position shown, the said pin 450 is in contact with one end of the groove 451, which is of such a length that the said groove and the said pin limit the motion of the circular plate 96 with respect to the circular plate 90 and thereby limit the extent of the adjustment which the adjusting mechanism may cause, the said pin 450 and groove 451 preventing the circular plate 96 from moving in a clockwise direction beyond the position shown in the drawings and preventing motion in a counter clockwise direction beyond the point which would bring the adjusting pistons in the circular grooves in the circular plates of the adjusting mechanism to a position where their opposite heads have approached each other to the same degree that their proximate heads occupy, as shown in the drawings, the range of motion here shown being greater than 270 degrees and less than 360.

Referring to the drawings, it is evident that when the eccentric bush 43 has been adjusted in a counter clockwise direction to the point where the real crank has no stroke and consequently the revolutions of the crank shaft 40 produced no pressure in the main fluid circuit, no fluid pressure is available from the main fluid circuit for use in the adjusting mechanism for causing further motion of the said eccentric bush 43 and, therefore, once the eccentric bush is brought to this position other means must be employed for operating the adjusting mechanism sufficiently to cause the real crank to be adjusted from its zero position to either side thereof. Referring more particularly to Figs. 1, 20, 21 and 22, I have previously stated that the delivery side of the leakage pump is directly connected to the port 300 of the pump valve chamber 255 and that, under normal working conditions, the said leakage pump delivers its fluid through the various ports and passages to the low pressure side of the main fluid

circuit. When, however, high pressure ceases to exist in the main fluid circuit, due either to the pump crank being adjusted to zero stroke or to any other cause, pressure ceases to act on the right hand end of the pump valve 271 and the spring 281, which has previously been compressed by the said valve 271 being forced to the left, re-acts against the valve and forces it to the right of the said chamber and against the stop 282 and in this position the head 272 of the said valve 271 covers the port 301, the head 273 at the same time uncovering the port 298 and the head 274 which has passed to the right of the port 297, has permitted it to connect through the radial holes 305 with the axial hole 325 in the said valve and thereby through the radial hole 304 in the valve stem with the port 300. Under these conditions, the delivery side of the leakage pump 240 is connected, through the radial hole 304, axial hole 325 and radial holes 305 and the port 297 in the pump valve chamber 255, to the constantly high pressure port 172 of the adjusting valve chamber 160; and the delivery side of the leakage pump is also at the same time connected through the port 300 and port 298 of the pump valve chamber and the channel 303, shown in dotted outline in Fig. 21, with the port 299 in the adjusting valve chamber 160. With the adjusting valve in the position shown fluid passing from the pump into this port 299 is free to pass between the heads 168 and 169 of the adjusting valve through the channel 314, channel 306 into the channel 296 where it is free to pass into the low pressure side of the main fluid circuit, but, when its pressure reaches the predetermined point to which the back pressure has been limited, it will open the valve 310 and pass into the interior of the casing 150. If, however, the adjusting valve 161 is moved to either side of the position shown in Fig. 20, which will be done when the operator desires to cause the adjusting mechanism to move the pump crank from its position of zero stroke the port 299 in the adjusting valve chamber 160 will be covered by the head 168, or the head 169, depending on the direction in which the said adjusting valve 161 is moved, and such covering of the port 299 will prevent communication between the leakage pump and the channel 296 and thereby prevent the leakage pump from discharging its excess fluid at the predetermined pressure, at which the valve 310 had been adjusted. The leakage pump will, therefore, raise the pressure in the port 300 and consequently through the above described connections, in the port 297 and the port 172 and such increased pressure from the leakage pump will then pass from the port 172 in the adjusting valve chamber 160 through either the port 170

or the port 171 into the adjusting mechanism where it will cause it to adjust the eccentric bush and thereby move the real crank to one side or the other of its zero position, depending on the direction in which the adjusting valve 161 is moved by the operator. As soon as the pressure from the leakage pump has thus been utilized to adjust the pump crank from its zero position, the pump crank itself will generate pressure in one side or the other of the main fluid circuit and such pressure so generated in the main fluid circuit will then pass, as previously described, through the various ports and connections into the pump valve chamber where, acting on the pump valve 271, it will force the latter to the left and thereby cause the leakage pump to be again connected as previously described to the low pressure side of the main fluid connection. It is thus seen that fluid pressure from the main fluid circuit is utilized for performing the adjustment of the stroke of the pump crank at all points except at the zero position, and that at the zero position of the said crank the leakage pump is automatically caused by the pump valve to be so connected to the adjusting valve chamber as to furnish fluid pressure for moving the pump crank from its zero position. In order to prevent the possibility of high pressure generated in the main fluid circuit from reaching the leakage pump should the pump valve be sluggish in its action and fail to disconnect the leakage pump from the high pressure port of the adjusting valve chamber before high pressure generated in the main fluid circuit reaches the said port 172, I have provided the chamber 249 formed on the side of the pipe 247 which under ordinary circumstances is prevented from communication with the pipe 247 by the valve 251 and the compression spring 252, the said compression spring 252 being made of such a degree of stiffness that while it prevents communication between the said chamber and the said pipe at pressures sufficient to operate the adjusting mechanism when the pump crank is at zero and, consequently, there is comparatively small resistance to adjustment of said crank, yet should high pressure from the main fluid circuit be carried over into the said pipe 247 before the pump valve 271 has closed communication between the leakage pump and the high pressure side of the main fluid circuit, the said valve 251 will open and permit such excessive pressure to pass through the pipe 253 into the interior of the casing 150 and thereby prevent such high pressure from reaching the leakage pump 240.

As previously described, the pump and the motor will run in the same direction and at the same speed when their various parts are adjusted to the positions shown in the

drawings. Such driving of the motor by fluid pressure generated in the pump, however, involves more or less friction due to pressure on the bearings and other causes and since in many applications a speed ratio of one to one between the pump and the motor is used for a considerable portion of the time that the apparatus is working, I have provided means whereby when the adjustment of the pump stroke is such as to cause the motor to be driven at approximately the same speed as the pump, the pump and motor shafts will be automatically clutched together and the work of driving the motor will therefore be performed by the clutch, thereby relieving the fluid circuit of pressure and consequently relieving the bearings of a portion of the pressure which would otherwise exist. The operation of this automatic clutch is as follows: When the adjusting mechanism is in the position shown in the drawings which is the limit of the clockwise adjustment as determined by the pin 450 and the co-acting groove 451, Figs. 1 and 12, the radial hole 394 in the inner circular groove 98 of the circular plate 96 is connected to the radial hole 393 which, through the axial hole 391 in the shaft 40, connects with the radial hole 392 and thence with the space between the cup-packings 382 and 387 in the counter-bore in the hub of the clutch 379. Since the elements of the adjusting mechanism as just stated are at the limit of their motion in the clockwise direction, fluid pressure admitted into the circular groove 98 will not cause further motion of the said adjusting mechanism and such pressure, so admitted to the circular groove 98, will be free to pass through the above connections and between the cup packings 382 and 387 and will force the clutch 379 toward the right in Fig. 1, clutching with the clutch 379' and thereby causing it to lock the shaft 40 to the shaft 40' and as soon as the tongues and grooves of the said clutch 379 have interlocked with the corresponding tongues and grooves of the clutch 379' the yoke 397 on the clutch 379 will, through the lever 400, cause the valve 409 in the valve chamber 403 which connects the by-pass pipes 401 and 402 to be moved toward the left in Figs. 24 and 27 and thereby cause the said pipes 401 and 402 to be connected together through the radial holes in the valve heads 410 and 411 and their co-acting tubular seats 407 and 408, thereby equalizing the pressure in the two sides in the main fluid circuit. As soon as the adjusting mechanism is moved in a counter clockwise direction causing the pump stroke to be decreased and thereby the motor to be driven at a less speed than the pump, the radial hole 393 in the shaft 40, Fig. 16, will be disconnected from the radial hole 394 in the groove 98, the said hole 393

being now connected to the crescent shape groove 395 formed in the bore of the circular plate 96, and the spring 390 acting between the collar 386 and the cap 389 will 5 force the clutch 379 toward the left, thus disengaging it from the clutch 379' and thereby disconnecting the pump shaft 40 from the motor shaft 40', such motion of the clutch 379 to the left forcing the fluid 10 from between the cup packings 382 and 387 through the radial hole 392, axial hole 391 and radial hole 393 in the shaft 40 into the crescent shaped groove 395 in the bore of the circular plate 96, whence such fluid 15 will be free to escape through the hole 460, Fig. 1, in the hub 97 of the plate 96 and thereby escape into the casing 150. At the same time that the clutch 379 moves toward the left and thereby disconnects the pump 20 shaft 40 from the motor shaft 40' the yoke 397 causes the upper end of the lever 400 to move toward the right allowing the valve 409, Figs. 24 and 27, to move under the actions of its springs, toward the right 25 thereby cutting off communication between the pipes 401 and 402, the said parts being so arranged that the valve 409 is caused to cut off said communication between the pipes 401 and 402 before the clutch 379 has 30 completely disengaged with the clutch 379' so that when the clutch does actually disengage the by-pass has been cut off and the motor shaft is actually being driven by fluid pressure delivered from the pump. 35 From the foregoing description it will be noted that the broad embodiment of my invention consists of a variable speed gear comprising a pump having a rotary element and a stationary element, and a motor with 40 similar elements, the rotary element of which is driven by the fluid delivered from the pump, with means for varying the volume of such fluid so delivered, whereby the motor is driven at variable speeds, combined with means for clutching the rotary 45 elements of the pump and motor together whenever the relative capacities of the pump and motor are in a predetermined ratio, or when the speeds of these two elements are 50 substantially equal; and in such a combination wherein the elements may be locked together while in motion and, further, in such mechanism wherein the clutch operating means not only effects the locking together 55 of the said rotary elements of pump and motor, when their speeds are substantially equal, but is capable of, and adapted to, unlock the said elements when their speeds are different, that is, when the capacity of the 60 pump is greater or less than the capacity of the motor; and, also, in such a pump and motor, with a single valve for controlling the ingress and egress of fluid for the pump, and means for varying the relative capacities 65 of pump and motor operated by fluid

pressure derived from the pump, with other subsidiary features and details of combination, as hereinafter set forth in the claims; and, therefore, while I have shown the preferred embodiment of my invention in the drawings, it is to be distinctly understood that I do not limit myself to the particular form of the different elements, or the specific combinations thereof, as it is evident that they may be all varied by substitution of mechanical equivalents and other elements, adapted to perform the functions set forth, without departing from the spirit or scope of my invention, as set forth in the said claims. 80

I claim as my invention:

1. A variable speed gear comprising a pump embodying a rotating element and a stationary element, a motor embodying a stationary element and a rotating element 85 driven by fluid pressure delivered from the pump, means for varying the volume of fluid delivered by said pump whereby the motor is driven at variable speeds, and means for clutching the rotating elements of the pump 90 and motor together when the speeds of the said rotating elements are substantially equal, substantially as described.

2. A variable speed gear comprising a pump embodying a rotating element and a stationary element, a motor embodying a stationary element and a rotating element driven by fluid pressure delivered from the pump, means for varying the volume of fluid 95 delivered by said pump whereby the motor is driven at variable speeds, and means for automatically clutching the rotating elements of the pump and motor together when the speeds of the said rotating elements are substantially equal, substantially as de- 100 scribed.

3. A variable speed gear comprising a pump embodying a rotating element and a stationary element, a motor embodying a stationary element and a rotating element 110 driven by fluid pressure delivered from the pump, means for varying the volume of fluid delivered by said pump whereby the motor is driven at variable speeds, and means operated by fluid pressure generated in the said 115 pump for clutching the rotating elements of the pump and motor together when the speeds of the said rotating elements are substantially equal, substantially as described.

4. A variable speed gear comprising a 120 pump embodying a rotating element and a stationary element, a motor embodying a stationary element and a rotating element driven by fluid pressure delivered from the pump, means for varying the volume of fluid 125 delivered by said pump whereby the motor is driven at variable speeds, and means operated by fluid pressure generated in the said pump for automatically clutching the rotating elements of the pump and 130

- motor together when the speeds of the said rotating elements are substantially equal, substantially as described.
5. A variable speed gear comprising a pump embodying a rotating element and a stationary element, a motor embodying a stationary element and a rotating element driven by fluid pressure delivered from the pump, means for varying the volume of fluid 5 delivered by said pump whereby the motor is driven at variable speeds, means for clutching the rotating elements of the pump and motor together when the speeds of the said rotating elements are substantially 10 equal, and means for by-passing the fluid pressure delivered from said pump, substantially as described.
6. A variable speed gear comprising a pump embodying a rotating element and a 20 stationary element, a motor embodying a stationary element and a rotating element driven by fluid pressure delivered from the pump, means for varying the volume of fluid delivered by said pump whereby the 25 motor is driven at variable speeds, means for clutching the rotating elements of the pump and motor together when the speeds of the said rotating elements are substantially equal, and means for by-passing the 30 fluid pressure delivered from said pump when the said rotating elements have been clutched together, substantially as described.
7. A variable speed gear comprising a pump embodying a stationary element co- 35 acting with a rotating element to generate fluid pressure, a motor embodying a stationary element and co-acting rotating element driven by fluid pressure generated in the pump, means for varying the volume 40 and the direction of the fluid pressure delivered to the motor by the said pump and thereby varying the speed and direction of rotation of said motor, and means for clutching together the rotating elements of 45 the pump and the motor when the direction of rotation of the two said elements are the same and when their speeds of rotation are substantially equal, substantially as described.
- 50 8. A variable speed gear comprising a pump embodying a stationary element and a co-acting rotating element, a motor embodying a stationary element and a rotating element driven by fluid pressure generated 55 in the pump, means for varying the relative capacities of the pump and the motor, and means for locking the rotating element of the pump to the rotating element of the motor when the capacity of the pump 60 is equal to the capacity of the motor and for unlocking it therefrom when the capacity of the pump is different from the capacity of the motor, substantially as described.
9. A variable speed gear comprising a pump embodying a stationary element and a co-acting rotating element, a motor embodying a stationary element and a rotating element driven by fluid pressure generated in the pump, means for varying the relative capacities of the pump and the motor, and means for locking the rotating element of the pump, while it is rotating, to the rotating element of the motor when the capacity of the pump is equal to the capacity of the motor and for unlocking it therefrom, when the capacity of the pump is different from the capacity of the motor, substantially as described. 65 70 75
10. A variable speed gear comprising a pump embodying stationary cylinders and co-acting rotating shaft, a motor embodying a stationary element and a rotating element driven by fluid pressure generated in the pump, means for varying the relative capacities of the pump and the motor, and means for locking the rotating shaft of the pump to the rotating element of the motor while both the said rotating parts are in motion, substantially as described. 80 85 90
11. A variable speed gear comprising a pump embodying stationary cylinders and a rotating shaft, a motor embodying a rotating element driven by fluid pressure from the pump, and a stationary element rigidly connected to the stationary cylinders of the pump, means for varying the relative capacities of the pump and the motor and adapted to change the direction of rotation of the rotating element of the motor, and means for locking the rotating shaft of the pump to the rotating element of the motor, substantially as described. 95 100
12. A variable speed gear comprising a stationary cylinder pump embodying a co-operating rotating crank shaft, a stationary cylinder motor embodying a co-operating rotating crank shaft driven by fluid pressure generated in the pump, means for varying the relative strokes of the crank shafts of the pump and the motor and acting to correspondingly vary the speed of rotation of the crank shaft of the motor, and means for locking together the two said crank shafts when their direction of rotation is the same and their speeds substantially equal, substantially as described. 105 110 115
13. A variable speed gear comprising a stationary cylinder pump embodying a co-operating rotating crank shaft, a stationary cylinder motor embodying a co-operating rotating crank shaft driven by fluid pressure generated in the pump, means for varying the relative strokes of the crank shafts of the pump and the motor and acting to correspondingly vary the speed of rotation of the crank shaft of the motor, and means for automatically locking together the two said 120 125

crank shafts when their direction of rotation is the same and their speeds substantially equal, substantially as described.

14. A variable speed gear comprising a driving mechanism embodying multiple stationary radial cylinders and a co-acting rotating crank acting as a pump, a driven device embodying a stationary element and a co-acting rotating element acting as a motor, means for varying the relative capacities of the pump and the motor, and means for locking the rotating crank shaft of the pump to the rotating element of the motor when the relative capacities of the pump and the motor are in a predetermined ratio, substantially as described.

15. A variable speed gear comprising a driving mechanism embodying multiple stationary cylinders, a coöperating rotating crank and a single rotating valve controlling the ingress and egress of fluid for all the cylinders, acting as a pump, a driven mechanism embodying similar coöperating elements, acting as a motor, and means for varying the relative capacities of the pump and motor, and adapted to change the direction of rotation of the motor, substantially as described.

16. A variable speed gear comprising a pump embodying multiple stationary cylinders, a coöperating crank and a single valve controlling the ingress and egress of fluid, a motor similarly constructed and driven by fluid pressure delivered from the pump, means for varying the relative capacities of the pump and the motor, and means for operating the said capacity varying means by fluid pressure derived from the pump, substantially as described.

17. A variable speed gear comprising a pump embodying multiple cylinders and a coöperating shaft, a motor similarly constructed and driven by fluid pressure delivered from the pump, means for varying the volume of fluid delivered by the pump and acting to correspondingly vary the speed of the motor driven thereby, means for operating the speed varying means by fluid pressure derived from the pump, means interposed between the said shafts for clutching together and unclutching the said shafts of the pump and the motor, and means for operating the said clutching and unclutching means by fluid pressure derived from the pump, substantially as described.

18. A variable speed gear comprising a pump embodying multiple cylinders and a coöperating shaft, a motor similarly constructed and driven by fluid pressure delivered from the pump, means for varying the volume of fluid delivered by the pump and acting to correspondingly vary the speed of the motor driven thereby, means for operating the speed varying means by fluid pres-

sure derived from the pump, means for bypassing fluid pressure from the pump, means interposed between the said shafts for clutching together and unclutching the said shafts of the pump and the motor, means for operating the said clutching and unclutching means by fluid pressure derived from the pump, and means for causing the clutching and unclutching means to open the said by-pass when the said pump and motor shafts are clutched together and for closing it when the said shafts are unclutched, substantially as described.

19. A variable speed gear comprising a pump, embodying a variable stroke crank, a single valve controlling the ingress and egress of fluid and operating in two predetermined angular positions with reference to the said tank, a motor driven by fluid delivered from the said pump, means for varying the stroke of the crank of the pump from a maximum to zero, means for maintaining the valve in one predetermined angular position with reference to the crank while the stroke of the said crank is varied from a maximum to zero, means for causing the angular position of the crank to shift one hundred and eighty degrees with references to the valve when the said crank stroke passes through zero to the other side thereof, means for varying the stroke of the crank from zero to a maximum after it has shifted one hundred and eighty degrees on passing through zero, and means for maintaining the valve in its second predetermined angular position with reference to the crank when the crank stroke is varied on this side of its zero position, substantially as described.

20. A variable speed gear comprising a pump embodying a variable stroke crank and a single valve controlling ingress and egress of fluid, a motor driven by fluid pressure delivered from the pump, means for varying the stroke of the crank of the pump from a maximum to zero, means for maintaining the valve at a predetermined angular distance from the said crank while it is varied from a maximum to zero, means operated by a fluid pressure for varying the stroke of the crank from zero through positions at a new predetermined angular distance from the said valve, means for collecting fluid leaking from the pump and the motor, a leakage pump automatically returning to the pump and motor the fluid leaking therefrom, and means for causing the said leakage pump to furnish fluid pressure for operating the crank stroke varying means at and very near to the zero point, substantially as described.

21. The combination, with a cylinder structure and a coöperating shaft and crank supported thereby, of means for adjusting the stroke of the said crank including an

- element fixed to said shaft coöperating with an element rotatable with reference thereto, and means for causing fluid pressure to operate the said adjusting means, substantially as described.
22. The combination, with a cylinder structure and a coöperating variable stroke crank comprising two elements, one of which is supported by and rotatable with reference to the other, of means for rotatably adjusting the said rotatable element of the crank with reference to its coöperating element including an element fixed to said rotatable element of the crank and an element fixed to said supporting element of said crank, and means for causing fluid pressure introduced between the two elements of said adjusting means to cause them to adjust the stroke of the said crank, substantially as described.
23. The combination, with a cylinder structure and a coöperating variable stroke crank, of a fluid pressure operated adjusting mechanism including two elements rotatably operatable with reference to each other by fluid pressure introduced between them, substantially as described.
24. The combination, with a cylinder structure and a coöperating variable stroke crank, of a fluid pressure operated adjusting mechanism including two elements rotatably operatable with reference to each other by fluid pressure introduced between them, and means for manually controlling the introduction of fluid between the two elements of the said adjusting mechanism, substantially as described.
25. The combination, with a cylinder structure and a coöperating variable stroke crank, of a fluid operated adjusting mechanism, including two elements rotatably operatable with reference to each other by fluid pressure introduced between them, and a manually operated balance valve for controlling the introduction of said fluid pressure, substantially as described.
26. The combination, with a cylinder structure and a coöperating variable stroke crank, of a fluid pressure operated adjusting mechanism including two elements rotatably operatable with reference to each other by fluid pressure introduced between them, a manually operated valve for controlling the introduction of fluid between the said elements of the adjusting mechanism, elements moving in synchronism with the said adjusting mechanism co-acting with said valve, and adapted to automatically return the said control valve to its initial position when the said adjusting mechanism has adjusted the stroke of the crank to the position indicated by the extent of the manual adjustment of said control valve, substantially as described.
27. The combination, with a cylinder structure and a coöperating variable stroke crank acting as a pump, of an adjusting mechanism comprising elements rotatable with reference to each other and operated by fluid pressure from the pump, substantially as described.
28. The combination, with a cylinder structure and a coöperating variable stroke crank acting as a pump, of an adjusting mechanism comprising elements rotatable with reference to each other and operated by fluid pressure from the pump, a valve mechanism, a manually operated control element connected to and operating said valve, and connections between the said adjusting mechanism and the said valve mechanism that automatically stop the adjustment of the said adjusting mechanism when it has varied the stroke of the crank to the extent indicated by the adjustment of the manually operated control element, substantially as described.
29. A variable speed gear comprising a pump, a motor driven by fluid delivered from the pump and which is returned by the motor to the pump, means for collecting leakage from the pump and the motor, and means comprising an auxiliary pump for returning such leakage and maintaining a predetermined back pressure on the fluid returned by the motor to the pump, substantially as described.
30. A variable speed gear comprising a pump, a motor driven by fluid delivered from the pump and returned thereto by the motor, means for collecting leakage from the pump and the motor, and means comprising an auxiliary pump automatically acting to return such leakage and to maintain a back pressure substantially higher than atmospheric pressure on the fluid returned by the motor to the pump, substantially as described.
31. A variable speed gear comprising a main pump embodying cylinders, pistons and a variable stroke crank, a motor driven by fluid delivered from the pump and returned by the motor to the pump, means operated by fluid pressure from the pump for varying the stroke of the crank from a maximum to substantially zero, means for collecting leakage from the pump and the motor, means comprising an auxiliary pump automatically acting to return such leakage and to maintain a predetermined back pressure on the fluid, and means for automatically causing the auxiliary pump to furnish fluid pressure for operating the stroke varying means when the stroke of the crank has been varied to a degree rendering the main pump incapable of furnishing fluid pressure to the stroke adjusting means, substantially as described.

32. A variable speed gear comprising a pump, a motor, a fluid circulated from the pump to the motor and returned by the motor to the pump, and means for maintaining 5 the fluid which is in circulation at a pressure substantially greater than atmospheric pressure, substantially as described.

33. In a fluid pressure pump or motor operating on or by a lubricating fluid and 10 comprising a cylinder structure, a reciprocating piston, a crank and an element connecting the piston to the crank and having a recess surrounded by a bearing surface in contact with said crank, means for introducing 15 lubricating fluid under pressure from the cylinder into said recess and thereby partially counterbalancing the pressure which would otherwise be transmitted from the piston to the crank, and a pressure reducing 20 guarding groove around said bearing surface for preventing fluid pressure leaking between said bearing surface and said crank from entirely counterbalancing the pressure between the piston and the 25 crank, substantially as described.

34. A pump or motor comprising a valve, a crank shaft embodying a crank pin formed intermediate of its length and eccentrically disposed with reference to the center of the 30 said shaft, an eccentrically bored bush mounted on said crank pin, two eccentrics formed on the said bush, one of which is concentric with the exterior of the bush and the other eccentric thereto twice the amount 35 of the eccentricity of the bore of the bush, means for rotatably adjusting the bush on the crank pin, and means for causing the two eccentrics on the bush to rotatably adjust the valve with reference to the said 40 shaft at one-half the angular speed that the bush is adjusted with reference to the said crank, substantially as described.

35. A pump or a motor comprising a valve, a crank shaft embodying a crank pin 45 formed intermediate of its length and eccentrically disposed with reference to the center of the said shaft, an eccentrically bored bush mounted on said crank pin, two eccentrics formed on the said bush, one of 50 which is concentric with the exterior of the bush and the other eccentric thereto twice the amount of the eccentricity of the bore of the bush, means for rotatably adjusting the bush on the crank pin, and a disk connected 55 to the valve having two diametrical slots in its face, slides working in said slots and co-acting with the two said eccentrics to rotatably adjust the valve with reference to the shaft at one half the angular speed that the 60 bush is adjusted with reference to the crank pin, substantially as described.

36. A pump or a motor comprising a valve, a crank shaft embodying a crank pin formed intermediate of its length and eccen-

trically disposed with reference to the center of the said shaft, an eccentrically bored bush mounted on said crank pin, two eccentrics formed on the said bush, one of which is concentric with the exterior of the bush and the other eccentric thereto twice the amount of the eccentricity of the bore of the bush, means for rotatably adjusting the bush on the crank pin, and a disk connected to the valve and having two diametrical perpendicular slots formed in separate planes 75 parallel to the face of the disk, slides working in said slots and co-acting with the two said eccentrics to rotatably adjust the valve with reference to the shaft at one-half the angular speed that the bush is adjusted 80 with reference to the crank pin, substantially as described.

37. In a fluid pressure variable speed gear comprising a pump and a motor and embodying a variable stroke crank, an adjusting mechanism operated by fluid pressure generated in the said speed gear for adjusting the stroke of the crank, a leakage pump automatically returning to the speed gear fluid leaking therefrom, and a system of 90 three valves interconnected by ports and passages and controlling the adjusting mechanism and the said leakage pump, substantially as described.

38. In a fluid pressure pump or motor the 95 combination of a variable stroke rotating crank shaft comprising two elements, one of which is fixed to said crank shaft and the other rotatable around said crank shaft, means operated by fluid pressure for varying 100 the stroke of said crank shaft, said means comprising an element rotating with said crank shaft and operating to rotate said rotatable element relatively to said fixed element.

39. In a fluid pressure pump or motor embodying a variable stroke crank pin carried by a crank shaft, adjusting means operated by fluid pressure for varying the stroke of the said crank pin, said adjusting 110 means comprising two elements one of which is fixed to the said crank shaft and the other rotatably mounted on the said crank shaft, substantially as described.

40. In a fluid pressure pump or motor embodying a variable stroke crank pin carried by a crank shaft, adjusting means for varying the stroke of the said crank pin, said adjusting means comprising two elements, one of which is fixed to the said crank shaft 120 and is provided with a piston in a groove and the other of which is rotatably mounted on the said crank shaft and is provided with a co-operating piston in a groove, and means for introducing fluid pressure between 125 said elements to effect the rotation of said rotatable element.

41. In a multiple cylinder fluid pressure

pump or motor, a rotating valve controlling the ingress and egress of fluid for all the cylinders and means for maintaining equal and opposite fluid pressure on said valve in all positions of rotation, substantially as described.

42. In a multiple radial cylinder fluid pressure pump or motor, a rotating valve controlling the ingress and egress of fluid for all the cylinders and means for maintaining equal and opposite fluid pressure on said valve in all positions of rotation, substantially as described.

43. In a fluid pressure pump or motor, embodying multiple cylinders radially arranged around a central chamber, a movable valve operating in said central chamber to control the ingress and egress of fluid from all the cylinders by its movement said valve being provided with symmetrically arranged ports subject to equal fluid pressure whereby said valve is balanced, substantially as described.

44. In a fluid pressure pump or motor, embodying multiple cylinders arranged around a central chamber, a valve mounted in said chamber, said valve comprising a port controlling the ingress of fluid to the cylinders, a port controlling the egress of fluid from the cylinders and balance ports formed in said valve, and subsidiary balance ports formed in the central chamber, co-acting therewith, whereby the said valve is balanced with reference to the fluid pressure, substantially as described.

45. In a multiple cylinder fluid pressure pump or motor, embodying a central chamber in which ports leading from the cylinders terminate, a valve rotating in said chamber, said valve comprising two diametrically opposite ports controlling the ingress and egress of fluid through the said cylinder ports, balance ports having passages connecting them to the ingress port of the valve and balance ports connected to the egress port of the valve, and subsidiary balance ports formed in the said central chamber, co-acting with said balance ports, whereby the said valve is balanced with reference to fluid pressure, substantially as described.

46. In a variable speed gear comprising a pump and motor of variable relative capacity, a fluid pressure operated mechanism for effecting the variations in capacity and the direction of flow of the fluid, said mechanism comprising a valve for directing the fluid from the pump to the adjusting mechanism, and operated to different positions upon change of direction of the fluid and an auxiliary pump for shifting said valve when there is no difference in pressure in the main circuit.

47. The combination with a driving shaft, of an eccentric mounted thereon, pumping mechanism driven by the eccentric, a device

operable by fluid pressure for adjusting the eccentric, a pump driven by the shaft for supplying fluid to operate said device, and a manually operable valve controlling the supply of fluid to said device.

70

48. In a hydraulic power transmission apparatus, the combination of a drive shaft, non-rotatable pumping mechanism driven by said shaft, a pressure pump, and means operated thereby to regulate the quantity of fluid delivered by the pumping mechanism.

49. In hydraulic power transmission apparatus, the combination with a drive shaft, of non-rotatable pumping mechanism driven by said shaft, a pressure pump, means operated thereby to regulate the quantity of fluid delivered by the pumping mechanism, and manually operable mechanism for controlling the operation of said means.

50. In hydraulic power transmission apparatus, the combination with a drive shaft, of non-rotatable pumping mechanism operated thereby, a fluid circulated by said mechanism, a motor driven by said fluid, a pumping device, and means associated therewith for regulating the output of the pumping mechanism.

51. A driving member and a driven member, a fluid power transmission device interposed between said members, said device comprising a pump, a fluid pressure motor, a rotary valve for directing pressure from the pump to the motor, and means for balancing said valve against lateral and end-wise fluid pressure.

100

52. A driving member and a driven member, a fluid power transmission device interposed between said members, said device comprising a pump, a fluid pressure motor, a rotary valve for directing pressure from the pump to the motor, a port in said valve adapted to be subjected to fluid pressure to effect a bodily movement of said valve in a direction perpendicular to its axis of rotation, and means for balancing said pressure by a counterpressure acting on the valve in a reverse direction.

105

53. A driving member and a driven member, a fluid power transmission device interposed between said members, said device comprising a pump, a fluid pressure motor, a rotary valve for directing pressure from the pump to the motor, a port in said valve adapted to be subjected to fluid pressure to effect a bodily movement of said valve in a direction perpendicular to its axis of rotation, a groove in the periphery of the valve opposite said port, and means for admitting fluid under pressure from said port to said groove to effect a balance of the said valve.

115

54. A driving member and a driven member, a fluid pressure power transmission device interposed between said members comprising a pump and a motor, a rotary valve arranged to direct a fluid between the pump

120

130

and motor, said valve being subjected to a pressure from the pump acting on the valve in a direction perpendicular to its axis of rotation, and means for directing a fluid pressure.
5 sure upon said valve in a direction to counterbalance the action of said first named

In testimony whereof, I have signed my name to this specification, in the presence of two subscribing witnesses.

CHARLES M. MANLY.
